BOTTLE FORMING MACHINE

Samuel E. Winder, Knox, Pa., assignor of one-half
to Henry C. Daubenspeck, Massillon, Ohio

Application August 5, 1946, Serial No. 683,470

31 Claims. (Cl. 49—9)

The present invention relates to a bottle forming machine. In this connection, the manufacture of bottles is the primary concern of the invention. However, it will be readily understood that many of its features may be applied to the production of other glass products, particularly container ware.

It is the prime object of this invention to provide a machine and a process by which such glass products may be made more rapidly. It is a further prime object of the invention to provide a process and a machine by which better quality glass products may be made with fewer rejects.

It is a further object of the invention to provide a machine and process of this kind which will rapidly produce the glass products in a continuous operation from a glass charging point to a ware removing point.

It is a further object to provide a method and machine that make more glass products per unit of time, but which may be operated with a minimum number of men. Particularly it is an object to provide such a method and machine having all of the operations that require attention available from one position, and having these operations sufficiently free of complications to be cared for by one man. To this end, it is an object to eliminate, to the maximum extent, interoperations of parts that require precise synchronization to obtain proper operation and satisfactory production of glassware. In particular, it is an object to eliminate the split-second synchronization of neck ring and mold opening and mold closing operations.

It is a further object to provide a method and machine that increase the output of ware per unit of time without great change in the mold rate, or time required for formation of an individual product from an initial charge of glass.

It is a further object to provide a method and machine having a cycle that may be speeded up or slowed down to change the production rate, particularly for adaptation to different sizes of ware. Specifically, it is an object to eliminate the speed limitation imposed by conventional transfer operations.

Another object is to provide a method and machine in which the amount of heat dissipation in the blank molds is a substantially larger proportion of the total heat dissipation for the entire cycle. Specifically, it is an object to provide a system wherein the transfer from blank to blow mold occurs after greater heat dissipation in the blank mold than has heretofore been accomplished with the present type of operation. A particular object is to reduce the ratio of time for making the finish on the ware to total time of the making of the parison in the blank mold.

A further object is to provide a method and machine making better bottles, with even walls and well finished bottoms. Specifically, it is an object to provide a system wherein temperature irregularities in a charge of glass are overcome to a greater degree, where neck ring checks are eliminated, and settle waves are minimized.

2

A further object of the invention is to provide a machine and a process for making glass objects in two separate stages of formation of a parison and subsequent formation of the object from the parison, wherein a relatively stiff parison is formed and transferred from the parison mold to the finish mold. A further object is to provide a machine and a process of this kind by which such relatively stiff parison is formed and transferred, and is subsequently reheated in the finish mold prior to its being finished to the completed ware. A further object is to form a parison, as aforesaid, and to transfer the same while holding it by a part that is not readily injured by the transfer mechanism, to employ a transfer mechanism and system that has a minimum tendency to damage the parison, and particularly a relatively stiff parison that is not as subject to deformation in the transferring operation as is a conventional parison.

A further object of the invention is to provide a machine and process of this kind which will transfer a parison while holding it by a portion relatively near to the center of gravity of the parison, so as to minimize the effect of inertial forces acting upon the parison in the transfer operation. Specifically, it is an object of the invention to provide a machine and a process of this kind wherein bottles or like container ware are formed, and in which the parison thereof is transferred while it is being held by the bottom of the parison. A further object of the invention is to provide a machine and a process of this kind wherein the parison is formed so as to be completed at the bottom in an area that will be a completed bottom part of the final glassware. A further object is to provide a parison that has substantially the length of the completed ware, and which has a supporting surface at its bottom, whereby it may be introduced into the finish mold and be supported at its bottom therein. Stated generally, on this aspect, it is an object of the invention to provide a machine and a process which eliminate the run or stretch-down of the parison in the finish mold. It is a further object of the invention to provide a machine and a process wherein a relatively stiff parison is formed so as to be supported at its top and at its bottom in the finish mold, and, while so held, is permitted to reheat in the finish mold prior to the introduction of the final finishing operations.

A further object of the invention is to provide a machine and a process of the foregoing type wherein a charge of glass is introduced into a blank mold and is very rapidly forced to the bottom of the blank mold so as to complete the finish of the ultimate ware onto the parison, and is promptly forced back into the blank mold to complete the parison with a minimum of dwell of the charge of glass in its forced down condition. A specific object is to cause the forcing back operation aforesaid to complete a section of the opposite end of the parison for the previously mentioned reasons.

A further object of the invention is to provide, particularly in a blow and blow type of machine, a relatively long counterblow operation for the parison, including sufficient time of dwell of the parison in the blank mold, so that it becomes relatively stiff, whereby it may be transferred with minimum damage, and whereby a better product may be produced. A further object is to provide a machine and a process wherein the relatively stiff parison is then transferred to a finish mold, is enclosed in said finish mold, and is permitted to dwell in said finish mold for a substantial period of time, during which it may reheat prior to the final forming operations in the finish mold.

A further object of the invention is to provide a machine and process of this kind wherein an over-all cycle for the formation of the glassware is divided between the formation of a parison and the formation of the com-

pleted ware, so that the formation of the parison comprises substantially one-half of the total time of the complete cycle.

A further object of the invention is to provide a single continuously operating machine for performing each and all of the foregoing objects. More particularly, it is an object of the invention to provide a continuous machine having two sets of molds thereon, both sets continuously rotating together, and with transfer mechanism for transferring the parison from one set of said molds to the other, and with timing mechanism to produce the cycle of said operations as aforesaid.

Another object is to provide a machine that secures tight fit of a vacuum head with the blank mold, and insures smooth opening of the blank mold. More particularly, it is an object to provide an arrangement of an air-flow head and a mold that secures a tight fit between them, prevents crashing of the parts, and insures proper alignment of the mold sections.

An additional object is to provide a system of this kind wherein the blow mold is automatically opened at the bottom for gravity dumping of anything remaining in the mold after a take-out operation.

A further object of the invention is to provide such a machine having transfer mechanisms of the type as aforesaid that will engage the heavier bottom part of the parison by vacuum, and swing said parison for introduction into a finish mold. A specific object of the invention is to provide such a transfer mechanism wherein a transfer head engages a finished bottom part of the parison, swings it into position to be received in a finish mold, and forms the said bottom part of the finish mold.

A further object of this invention is to provide a machine of this kind wherein there is a base with an upstanding central column thereon, and a framework rotatably mounted upon the base and having stabilized bearing on an upper part of the central column, which framework constitutes the support for the blank molds, the transfer mechanisms, the finish molds, and the associated parts thereof.

A further object of the invention is to provide a machine of this kind having a minimum of separately designed parts and a maximum of interchangeable parts. A particular object is to have mold and transfer units that are readily removable as units, and that are interchangeable. Specifically, in this connection, it is an object of the invention to provide blank molds and finish molds with interchangeable mounting parts, interchangeable power operating parts, and interchangeable valve controlling parts. A further object of the invention is to provide quickly operating aligning means for insuring the proper relative disposition of the several parts, together with securing means by which the parts may be attached together.

A further object of the invention is to provide a machine of this kind wherein alterations and changes necessary to the production of different sizes and shapes of ware may quickly and easily be made.

A further object of the invention is to provide for the ready adjustment of the coordination and timing of the several operations, and particularly to provide convenient means for adjusting the timing operations while the machine is in operation.

A further object of the invention is to provide a transfer mechanism which swings the parison from the blank to the finish molds, together with means for regulating the deceleration of the transfer mechanism as it is moving the parison to its final position for enclosure in a finish mold.

A further object of the invention is to provide a desirable air distribution means. A particular object of the invention is to provide an air distribution means wherein air may be received in the central column and distributed therefrom without leakage. A further object of the invention is to provide such an air distribution system in-

volving a plurality of air manifolds that may conveniently be connected to the several operating devices of the machine.

A further object of the invention is to provide a convenient vacuum means for the operations involved, which vacuum means includes a rotating vacuum chamber from which connections may be made to the parts requiring vacuum.

A further object of the invention is to interrelate the 10 vacuum and air operating parts with maximum compactness and yet maximum accessibility for repairs and the like.

A further object of the invention is to provide a convenient system of distributing cooling air to certain parts 15 of the machine that require cooling.

A general object of the invention is to provide all of the foregoing features in a single composite machine requiring a minimum of floor area. A further object of the invention is to provide such a compact machine, in 20 which parts requiring lubrication are accessible at any time.

In the drawings:

Fig. 1 is a top plan view of a bottle forming machine embodying the present invention, some of the flexible tubing for the various valves being omitted in the interest 25 of clarity;

Figs. 2 and 3 are vertical radial sectional views taken approximately on the lines 2—2 and 3—3, respectively, in Fig. 1, the two sections in the aggregate comprising a 30 substantially diametrical vertical sectional view through the entire machine, certain portions of mechanism in the background being omitted, also in the interest of clarity;

Fig. 4 is a partial plan view partly in section, illustrating the means for manually adjusting a series of cam assemblies mounted near the top of the central column, the view being indicated by the line 4—4 in Fig. 3;

Fig. 5 is a side elevational view of one of a series of baffle arm operating cylinders and its associated roller operated valve;

Fig. 6 is a top plan view of the base portion of the machine only, having mounted thereon the driving mechanism, and a series of adjustable roller tracks for operating the plunger cylinders and vacuum valves;

Fig. 7 is a vertical cross-sectional view through the 45 base and pit therebeneath only, particularly illustrating the means whereby cooling air and suction are supplied to the machine;

Fig. 8 is a fragmentary plan view on an enlarged scale of the track adjustment in the lower right hand corner portion of Fig. 6;

Fig. 9 is a vertical sectional view on the line 9—9 of Fig. 8;

Fig. 10 is a detail view of one of the adjustable roller tracks appearing in Fig. 8;

Fig. 11 is a reproduction on an enlarged scale of a portion at the left center of Fig. 6, illustrating an adjustable assembly of roller tracks for operating the plunger valves, vacuum valves, and baffle cylinder valves;

Figs. 12, 13 and 14 are vertical sectional views taken 60 on the lines 12—12, 13—13 and 14—14 in Fig. 11;

Fig. 15 is a fragmentary enlarged view of a portion of Fig. 2 just above the section 18—18 at the center column, particularly illustrating the construction of the compressed air distributor of the machine;

Fig. 16 is a horizontal sectional view on the line 16—65 16 in Fig. 2;

Fig. 17 is an isometric view of one of the blank cylinder centering brackets;

Fig. 18 is a horizontal section illustrating the blank 70 mold mechanism, the plane of the section being approximately indicated by the line 18—18 in Fig. 2;

Fig. 19 is a plan view of the revolving table of the machine with portions of the top wall thereof broken away;

Fig. 20 is a fragmentary horizontal sectional view

comprising approximately the right hand portion of Fig. 18, or an enlarged scale, certain parts of Fig. 18 being sectioned differently;

Fig. 21 is a vertical tangential section taken on the line 21—21 at the top of Fig. 20, illustrating the valve mechanism for controlling the vacuum to the transfer head;

Fig. 22 is a bottom plan view of a valve member incorporated in a number of the valve constructions;

Fig. 23 is a side elevation of one of the plunger cylinder valve and counterblow valve assemblies, the view being taken on the line 23—23 at the right center of Fig. 20;

Fig. 24 is a vertical sectional view through the plunger cylinder valve taken on the line 24—24 at the right center of Fig. 23;

Fig. 25 is a detail view, partly in section, of a valve body included in the assembly of Fig. 23;

Fig. 26 is a vertical sectional view taken approximately on the line 26—26 at the right center of Fig. 20;

Fig. 27 is a vertical sectional view taken approximately on the line 27—27 at the right center of Fig. 20;

Fig. 28 is a bottom plan view, partly in section, of the valve body shown in Fig. 25;

Fig. 29 is a vertical section on the line 29—29 at the upper center of Fig. 20, illustrating in particular one of the baffle cylinder valves;

Fig. 30 is a horizontal sectional view on the line 30—30 in Fig. 29;

Fig. 31 is a detail view, partly in section, of one of the baffle cylinder constructions;

Fig. 32 is a horizontal sectional view on the line 32—32 of Fig. 31;

Fig. 33 is a reproduction of the lower left hand portion of Fig. 2 on an enlarged scale, showing parison or blank forming mechanism;

Figs. 34, 35, 36 and 37 are horizontal sectional views taken on the lines 34—34, 35—35, 36—36 and 37—37 of Fig. 33;

Fig. 38 is a top plan view of a finish or neck ring segment;

Figs. 39 and 40 are vertical radial sectional views of the finish ring taken on the lines 39—39 and 40—40 in Fig. 38;

Fig. 41 is a reproduction on an enlarged scale of the lower right hand corner of Fig. 3, showing parison forming mechanism in an operating stage different from that of Fig. 33;

Fig. 42 is a top plan view of a baffle arm for the parison mold, that is adjustably mounted on the upper end of a baffle cylinder shaft;

Fig. 43 is a side elevational view thereof;

Fig. 44 is a horizontal sectional view on the line 44—44 in Fig. 43;

Fig. 45 is a detail view of an adjustment lock nut for the baffle head;

Fig. 46 is a horizontal sectional plan view on the line 46—46 about half way up the column in Fig. 3, illustrating an adjustable cam assembly for operating the valves controlling the opening and closing of the blank molds;

Fig. 47 is a reproduction on an enlarged scale of the central right hand portion of Fig. 3, showing the finish mold, the transfer operating means, and part of the blank mold operating means;

Fig. 92 is a schematic layout illustrating the flow of compressed air, vacuum, and cooling air for the machine; and

Fig. 93 is a diagrammatic layout illustrating the cycle of operation.

Description of the machine base

This machine is adapted to be mounted upon a movable base 125. This base is generally rectangular in horizontal shape, as appears in Fig. 6 as well as in Fig. 1, and it comprises an upper table-like surface and side flanges. Suitable wheels 126 are located at the corners, being mounted on brackets attached to the base 125. The machine may be rolled on these wheels. The brackets also support jack screws 127 that may be turned down when the base is properly located, so as to keep it from moving.

The base is adapted to be rolled over a pit, preferably one with solid walls. Such a pit is shown at 128 in Fig. 7. This pit may form a conduit for the reception of a cooling air duct 129 that extends upwardly so as to be united with a downwardly extending circular flange 130 on the center of the base 125. This flange 130 provides a central opening 132 leading upwardly through the table and around the upper edge. The opening 132 also receives a vacuum pipe connection 134. This line may extend down through the duct 129 and then outwardly through the wall thereof, as shown in Fig. 7. It ultimately is connected to a vacuum source.

The base 125 supports a composite central column, generally designated 136, about which operating parts revolve. This column includes a round bottom part 137, having a center opening 138 with a ridge around it to interfit with the groove at the top of the opening 132 in the base 125. This arrangement locates the upper parts relative to the base, and provides for air flow from the base into the bottom of the column. The lower column part 137 has a flange around its lower periphery, through which screws 139 pass to secure the column to the base 125. The lower column part 137 has a lower cylindrical vertical wall portion 140 extending upwardly from its bottom and joined by a horizontal section 141 to a smaller, intermediate, cylindrical vertical wall section 142. The intermediate wall 142 is capped by a partition 143. Above the partition 143, there is an upper cylindrical wall 144, slightly smaller than the intermediate wall, to provide a shoulder between them. This upper wall is flanged inwardly at the top and has a top opening 145.

It will be seen that the upper end of the vacuum pipe 134 is secured in the partition 143. It divides the cooling air manifold from the vacuum outlet manifold, both of which are partly formed in the bottom column member 137. The cooling air manifold chamber is indicated at 150, being below the partition 143; and the vacuum exhaust manifold above the partition 143 is designated 151. The ledge 141 provides a plurality of openings 152 that comprise outlets from the cooling air manifold 150. The upper extension 144 has a plurality of ports 153 that provide inlet ports to the vacuum ex-

haust manifold 151. The ports 153 are four in number around the axis of the columns.

From the top of the extension wall 144, there extends the upper column part 165. This column is flanged at its bottom and is provided with a circular projection that fits into the opening 145 at the top of the wall 144 and insures location of these parts. It is held onto the wall 144 by screws, as shown in the drawings.

The upper column 165 has a plurality of different external diameters, all of which are joined by collar-retaining shoulders. These, in ascending order, are designated at 167, 168, 169, 170 and 171. Each of these various sections receives some relatively immovable parts of the operating mechanisms, which cooperate with parts that move around the column for their several operations.

Revolving table

At the bottom of the machine, there is a revolving table 190, shown in plan view in Fig. 19 (Sheet 6). This revolving table has a bottom wall 191 and a top wall 192. The top and bottom walls are joined by a circular hub wall 193 that is adapted to fit around the intermediate upstanding circular wall 142 of the lower column member 137. The rotating table also has an outer circular wall 194, and, spaced inwardly from the wall 194, another circular wall 195. The two outer walls 194 and 195, together with the top and bottom walls, provide an outer, annular vacuum chamber 196.

Extending between the inner wall 193 and the intermediate wall 195 are a plurality of radial reenforcing webs 197 that divide the space between the walls 193 and 195 into a plurality of sectorial chambers 200, designated as 200a to 200j, inclusive. (As there are ten mold sets on this machine, all identical, the reference numbers will be applicable to the corresponding parts of any one set. At times, the several sets and their component parts will be distinguished by the suffix characters a through j, the a set being at the nine-o'clock or charging position in the drawings.)

Each of the webs 197 has a boss 202 that has a hole 203 drilled down into it from the upper surface of the table. These holes 203 are accurately disposed around the table, for a purpose to appear. Alternate webs have bosses 204 toward the hub wall 193, and bosses 205 somewhat further out than the bosses 204. The inwardly spaced bosses 204 have holes drilled all the way through them, whereas the outwardly spaced ones 205 are drilled and tapped upwardly from the bottom.

The outer surface of the wall 194 of the table is provided with a plurality of flat portions 206a to 206j, inclusive, for the reception of mold head parts, as will appear.

The bottom wall 191 of the rotating table is provided with a plurality of air inlet openings 207a through 297j, there being one such opening for each of the sectorial chambers 200a through j, respectively. These inlet ports 207 are adapted to register at all times with the ports 152 leading from the shelf 141 on the lower column member 137. Each of the sectorial chambers of the table is also provided with an outlet in the form of an opening 208, there being ten such openings 208a through 208j. These openings 208 are accurately sized and spaced around the table.

The top wall 192 of the rotating table is also provided with a series of openings 209 leading into the annular chamber 196 opposite the end of each of the radial webs 197. They are accurately sized and spaced around the table, and constitute means used in aligning molds on the table 190. On an approximate radial line with the openings 209, the bottom wall 191 of the table is provided with a plurality of openings 210, one for each of the webs, as shown at 210a through 210j. Additionally, the annular chamber 196 is provided with a plurality of openings 211a through 211j in its top wall 192, with aligned

openings 212a through 212j through the bottom wall (Figs. 19 and 21). The purpose of these several openings is to receive and position valves, as will appear.

The table 190 is supported on a gear 215 attached to its lower surface. This gear is provided with an open center, so that it may fit over the lower section 140 of the lower column member 137. A plurality of screws 216 extend upwardly through the gear 215 and engage in the openings in the bosses 205 formed in the webs 197 of the rotating table. Also, screws 217 extend downwardly from the top through the webs 204 of the rotating table and engage in the gear 215. The gear, as appears in Figs. 2 and 3, has an annular ridge on its upper surface that interfits with a smaller ridge on the lower surface of the rotating table, so that the parts hold together securely and in proper relationship.

The gear 215 is supported upon a roller bearing, generally indicated at 220, the same including conventional bearing races and rollers of annular shape that fit around the outside of the vertical wall 140 of the lower column member 137 and support the table and associated parts on the extending flange of the column member 137, which, in turn, rests upon the base. The bearing 220 provides for proper centering of the parts as well as for reducing the friction while the table, and the parts it supports, rotate.

The gear 215 is adapted to be engaged by a driving gear 225 (Figs. 2 and 6) that is supported upon a vertical shaft 226, upon which is mounted another gear 227 driven by a worm wheel 228 on a driving shaft 229. The shaft 226, the gear 225, and the parts through the worm 228 are enclosed in and supported in a housing 230 that is held by screws to the base member 125. The shaft 229 extends out through a coupling and a bearing 231 to another bearing 232 on an extension 233 bolted to the base 125. A suitable drive for the shaft 229 may be provided. The one here illustrated is a chain drive 234, the chain being driven from some suitable power source not shown.

It will be seen that, when the chain operates, the shaft 229 is rotated, and this ultimately, through the gears 225 and 215, causes the movable table 190 to rotate about the column.

Blank molds

The machine has ten blank or parison molds. Each blank mold unit is mounted on a block 236. The series of these blocks are designated 236a through 236j. The blocks are shown separately in Figs. 68-70 (Sheet 14). Each has an outer section providing a vertical sleeve 237 with an opening 238. This outer section has a bottom flange 239 by means of which screws 240 may attach the same to the rotating table 125. The top 241 of the sleeve receives adjustable hinge collars, as will appear. The block projects backwardly, with an overhang 242. The overhanging part is accurately finished on sides and bottom at 243, to be received in a positioning block or yoke, as will appear. The overhang has a transverse key slot 244 across its upper surface.

Each hole 238 receives a mold hinge pin 245 with a press fit. The pin 245 has an enlarged intermediate threaded portion 246 which is brought down against the block 238. In this position, its bottom end is engageable in the hole 209 to aid in alignment of the molds on the table. A threaded collar 247 engages over the threads 246, and, in turn, receives a clamp 248. This clamp 248 is a split ring that may be drawn tightly about the collar 247. It has an ear adapted to engage in a notch 249 in the block 236, to clamp the attached parts against rotation. The collar 247 is adjustable, while the clamp is loose, to regulate the height of the mold. After proper adjustment is made, the clamp ring 248 is tightened.

A yoke 250 has a bottom pin 251 engageable in a hole 203, and an upper cradle 252 to accurately receive and locate the finished surfaces 243 of the block 236 (see Fig.

17, Sheet 5). The yokes combine with the hinge pins to give complete, accurate fitting of the parts together in a simple way. After they are thus fitted, the screws 240 are tightened.

5 Each parison mold, of which there are ten in this machine, is generally designated at 253, and includes a pair of mold halves 254 and 255. The mold section 254 has arms that provide spaced hinge collars 256, connected as shown in Fig. 3. The other mold section 255 is provided with spaced hinge ears 257, connected as shown in Fig. 2. The several ears are interspaced over the hinge pin 245.

10 The two mold halves 253 and 254 thus may swing about the pin 245 to open or to close. The operation of the molds to open or closing position is obtained by a yoke member 258. This yoke 258 has opposed arms that engage the respective mold halves through suitable links 259.

15 The shank of the yoke member 258 constitutes a piston rod having, at its inner end, a piston 260. This piston is contained within a cylinder 261 that is supported on the top of the mold block 236 and is positioned thereon by a key 262 that interengages with the groove 244 of the block 236 and a related groove 263 in the bottom of the cylinder. This provides radially accurate positioning of the cylinders on the blocks. Lateral positioning is obtained by depending flanges on the sides of the cylinder castings that depend over the sides of the blocks 236. These flanges are not shown for these cylinders, but will appear in the description of similar cylinders. The cylinders are finally secured in position by screws.

20 The piston rod has an extension 264 thereon that is journaled in a bushing 265 contained within a head 266 that closes the end of the cylinder 261. An additional cap 267 is provided over the end of the cap to hold the journal 265 in place and yet to permit its replacement (see Fig. 47, Sheet 11).

25 The piston 260 is operated by air that is supplied to its opposite ends under the control of a slide valve, generally indicated 270, that operates within a valve housing 271. There is one valve housing 271 secured to the top of each of the cylinders 260, and, therefore, there is one such valve housing for each set of parison molds.

30 Each valve housing 271 is located in endwise accuracy on the cylinder by a plug 272 engaged in grooves in the top of the cylinder 261 and the bottom of the valve housing 271. Each valve housing is flanged at its sides, to depend over the side edges of the top of the cylinder, and thereby to secure proper lateral location of the valve on the cylinder. The valve housing is finally secured to the cylinder by screws, as will appear in connection with other like valves in the machine.

35 The valve housing 271 has a cylindrical bore therethrough, in which a valve plug 274 slides. This cylinder is closed at one end by a head 276 that is held thereon by screws. This head receives an air inlet line 277 that is threaded thereinto and secured by a lock nut 278. The air is thereby delivered to the cylindrical housing at one end of the plug 275.

40 The cylinder is provided with two exhaust ports 279 and 280 that are shown in dotted lines in Fig. 47. As these extend forwardly from the plane of the sheet in that drawing, they will appear more clearly in connection with identical valve parts used with certain other parts of the machine.

45 The valve plug 275 contains an axial bore 282 that opens toward the inlet line 277, and, at its inner end, registers with a radial port 283. It has also another transverse radial port 284. In addition to these ports, the valve plug has two peripheral exhaust grooves 285 and 286.

50 The valve housing 271 and the cylinder 261 have registering openings that provide air passages 287 and 288 that lead into the opposite ends of the cylinder 261.

55 The valve plug 275 projects from the end of the housing 271 and carries, at its outer end, a cam roller 291, in

the manner shown. It also has a guide roller 292 held thereon by a screw 293, this roller reciprocating within a slot 294 in an arm projecting from the top side of the housing 271. This roller prevents rotation of the valve parts, and limits the linear movements of the plug.

In Fig. 47, the valve is shown as actuated to a left hand position toward the column, under the influence of the air acting against the right hand end of the plug 275. This air has moved the plug 275 as far to the left as it can go, until the roller 292 has reached the extreme of the slot 294. In such position, the air has flowed through the passage 282 and the passage 283 to the passage 287, where it has acted against the left hand end of the piston 260. In the meanwhile, the foregoing position of the valve has disposed the exhaust groove 286 in registry with the passage 288 from the right hand end of the cylinder, so that the air contained on the opposite side of the piston 260 is exhausted out the exhaust port 280.

Subsequently, the cam roller 291 will come in contact with its cam track and the valve will be forced in the opposite direction to the right against the pressure of the air entering the inlet line 277. When this happens, the port 283 will be displaced from the passage 287, but the air port 284 will be brought into registry with the other passage 288 leading to the right end of the piston. The peripheral exhaust groove 286 will be removed from registry with its exhaust port 280, and the peripheral groove 285 will be brought into registry with the exhaust passage 279 and the passage 287. As a result of the foregoing, the air entering the air line will then pass through the passage 282 in the valve, the passage 284, and the passage 288 to the right hand end of the piston 259, forcing the same to the left. The air on the opposite face of the piston will exhaust through the passage 287, the peripheral groove 285, and the exhaust port 279.

Blank mold operating valve cam

In the machine shown, there are ten mold sets, and hence ten valves 270. The various valves 270 are sequentially operated by being rotated to bring their cam rollers 291 against a cam arrangement that is mounted on the center column 136. This cam arrangement is shown in Figs. 2, 3 and 46 (Sheet 10), the last named showing the greatest detail. It includes a cam sector, generally indicated at 300, that is provided with two semi-circular hub sleeve parts 301 and 302 clamped around the portion 165 of the column 136 by screws 303. It will be seen that the cam parts may be conveniently removed by withdrawing the screws 303.

The outer edge of the cam sector 300, defined by a vertical arcuate wall 304, receives an arcuate cam plate 305 held to its outer edge by screws 306 extending upwardly from the bottom of the ledge. This cam plate is shown in Fig. 46 as having a sloping left end, and it will be seen that it terminates at its other end immediately beyond the most counterclockwise of its four attaching screws 306.

The cam sector also has an adjustable cam plate 307 that lies over the cam plate 305. This plate 307 provides the point of starting of the cam operation, and, therefore, it extends counterclockwise of the end of the plate 305. However, it terminates in a clockwise direction short of the end of the plate 305, so that the latter will take care of the ending of the cam operation.

The plate 307 has a pair of slots 309 that receive screws 310 that extend into and are secured to the sector 300. These screws permit adjustment of the plate 307 arcuately along the sector.

The foregoing adjustment is made by a mechanism including a link 311 that is pivoted to the clockwise end of the plate 307. The link is also pivoted to a rocker arm 312 pivotally mounted at 313 on the sector. This rocker arm, in turn, carries one end of a link 314 that is pivoted to a crank arm 315. This crank arm is pivotally mounted to the half ring 302 and is non-rotatably en-

gaged by a crank shaft 316. This shaft extends upwardly adjacent the column to the top of the machine, wherein, as shown in Fig. 4, it passes through a table 318 that is supported at the top of the column in a manner to appear later. Above the table 318, the shaft 316 is non-rotatably connected with a gear 319 which, in turn, meshes with a worm 320 held on an adjusting shaft 321 that is supported in a bearing 322 attached to the top of the table 318. The shaft 321, as shown in Fig. 1, projects outwardly and has a knurled wheel 323 at its outer end. This knurled wheel is conveniently located at the top of the machine for adjustment purposes.

It will be seen from the foregoing that the rotation of the knurled wheel 323 will provide for the arcuate displacement of the plate 307 so as to regulate the starting points of the cam operations of the blank mold opening and closing valves.

Blank mold heads

20 The blank molds are closed by vacuum finishing mechanisms, shown in Figs. 2, 3, 33 (Sheet 9), and 41 (Sheet 10), together with other figures wherein details appear. There is one such mechanism for each of the blank molds. These closing parts are attached to the outer edge of the 25 rotating table 190. As already noted, the rotating table is provided with a plurality of vertical flat portions 206. These furnish bases upon which to mount the supports for the mold closing means.

As shown in Figs. 20, 23, 26, 33 and 41, each vacuum 30 finishing mechanism has a supporting bracket 330 attached to one of the flat portions 206. Reference to Figs. 33 and 41 will disclose that the revolving table is provided with a locating pin 331 extending outwardly from each of the flat portions 206. Each pin has a 35 head that is adapted to interfit into an opening 332 in the inner face of the associated bracket 330. The pin cooperates with an interfitting of certain associated parts, to provide for the accurate locating of the bracket relative to the other parts. When the brackets are properly located, they may be secured into their proper positions by screws 333 that extend inwardly to the table. Other securing means will appear in the description to follow.

Each supporting bracket 330 is provided with a circular threaded opening on a vertical axis. This opening 334 extends downwardly from the top of the bracket and opens into an annular vacuum chamber 335, in the middle of which there is an upstanding frusto-conical tubular sleeve 336 that is adapted to receive a plunger incorporating a slide valve, as will appear. A passage 337 leads from the chamber 335 downwardly and inwardly to the depending side of the bracket 330.

Below the chamber 335, the supporting bracket 330 has a cylinder 340, that is closed at its bottom end by a cylinder head 341 that is held thereto by screws 342. 55 An air piston 343 is adapted to reciprocate within the cylinder 340, and is urged in a downward direction in the drawings by a coil spring 344 acting in a suitable recess in the bracket 330.

The piston 343 is connected to a combined valve and 60 piston rod 345 that reciprocates in the sleeve 336. A bleeder port 346 opens from the space above the piston, to relieve any trapped air in that space.

The operation of the piston 343 is controlled by a valve mechanism that is mounted on the side of the supporting bracket 330, as shown in Figs. 20, 23 and 26. There is a valve housing 348 held to the side of the supporting bracket 330 by screws 349, after it is properly located by a pin 350 that fits in keyways in the interfaces of the parts. This valve housing has an air pressure inlet 351 that opens into a cylindrical bore 352 that extends from adjacent the top of the housing to the bottom thereof. An exhaust passage 353 leads from the side of the housing.

A slide valve 354 reciprocates within the bore 352. 70 This valve projects from the bottom of the bore 352

and has a cam roller 355 secured to its bottom end, as shown in Fig. 24. The valve is held non-rotatably in the valve casing 348 by a cross pin 356 that is secured by a setscrew 357, accessible upon removal of the roller 355. The pin 356 reciprocates in slots 358 in the housing 348, so that the valve cannot rotate and is limited as to the extremes of its vertical movement.

The upper part of the valve plug 354 has an axial opening 360 extending partially down from the top thereof. From the bottom of the opening 360, an opening 361 leads radially outward to the surface of the plug.

Above the opening 361, there is a peripheral exhaust groove 362 extending around the plug, and, as shown in Fig. 26, capable of registration with the exhaust line 353. The valve housing 348 has a port 363 in it that is shown in Fig. 26 as registering with the exhaust groove 362. However, when the valve piston 354 is elevated, the exhaust groove is withdrawn from the exhaust port 351 and the inlet passage 361 is caused to register with the port 363 and admit air under pressure thereto. The opening 363 leads to the bottom of the cylinder 340.

The inlet air line 351 has a needle valve 368 interposed in it, so that the inlet flow to the piston may be regulated during operation of the machine. This will regulate the speed of the upstroke of the piston and attached parts. The valve 354 may have a spring above it to urge it downwardly, though usually the air flow will be adequate under all conditions of adjustment of the valve 368 to insure proper down travel of the plug.

It will be evident that, when the valve plug 354 is down to the position shown in the drawings, the piston 343 may descend, ejecting the air below it outwardly to the exhaust line. But, when the plug 354 is raised, compressed air passes through the passages 360, 361 and 363 to the piston to elevate it against the spring 344, this elevation taking place at a speed determined by the setting of the needle valve 368, and hence by the delivery rate of compressed air to the cylinder 340. Air pressure acts on the top of the valve 354 and constantly urges it downwardly. It is raised by a cam action to be described.

The plunger 345, that is operated by the piston 343, extends upwardly through the conical sleeve 336 of the support casting 330 and provides a valve portion 380. This valve will be described in detail hereafter. At its upper end, the plunger 345 has (for molds shorter than a maximum size) a tubular extension 381 that fits down over a reduced top of the plunger and is held thereon by a pin 382. It is encased in a cylindrical spacing sleeve 383 (likewise used when short molds are used), having a depending skirt 384 that is fitted over a long area into an externally threaded collar 385, thereby assuring an air tight but movable fit. This collar 385 is fitted into a threaded opening in the support bracket 330, and may be adjusted vertically therein by rotating it so that the threads move it up or down, as the case may be, relative to the support bracket. To hold the parts in adjusted position, the collar 385 has a milled flange 386 that is engageable by the end of a dog 387 pivoted between two ears 388 on the outer side of the support 330. A coil spring 389, duly confined by a pin and indentations, as appears in Fig. 33, is provided to maintain the end of the dog 387 into engagement with the adjacent notch on the milled rim of the collar 385.

The spacer sleeve 383 has a partial partition across it, which is provided with an annular set of holes 392 that are arranged around a cylindrical bore 393, in which the upper tubular extension 381 of the piston rod 345 operates and obtains a bearing.

The spacer sleeve 383, at its upper end, receives a cap 395 that has a depending skirt with a close sliding fit into the top of the sleeve. The upper inner diameter of the sleeve is the same as the inner diameter of the collar 384, so that the sleeve may be omitted. This cap 395 has a plurality of ports 396 arranged in a circle therein. It has a center bore 397 to receive a plunger, and a

flanged head 398 projecting from its upper surface. This upper surface is adapted for close fit with the mold sections. The projecting head is designed to interfit closely with complementary openings in the mold halves and neck rings.

The head 398 has a flange 399 that has a sloping cross section. Its sides descend, as shown. Above the flange, the head has a projection that enters the neck rings to cooperate in the formation of the finish. By this arrangement, when the mold halves close over the head 398, their overhanging parts will engage under the sloping surfaces of the flange 399, and will draw the head up slightly insuring a tight fit of the parts, and, at the same time, securing accurate positioning of the two mold parts, as they both are located around the head 398 and its flange. The skirt of the cap member engages the spacer 383 with such a fit and over such an area as to permit the foregoing without breaking the seal between the cap and spacer.

The cap 395 has a plurality of passages 400 that establish air flow paths around it. These passages are shown (Fig. 36) as eight in number. They are formed as grooves leading from the tops of the passages 397, following the contours of the surface of the cap and its head 398, until they terminate in shallow ends (such as .002" deep) opening adjacent the bottoms of the neck rings at the finish.

The center bore receives a plunger member 401 that is secured to the top of the spacer extension 381 of the piston rod 345. The plunger 401 fits over a projection 30 on the top of the extension 381 that is identical with the projection on the plunger 345, and is held thereto by a pin, as shown. The plunger has a shaping plug 402 on its upper end, and around this pin are a circle of openings 403.

It will be understood that the plunger plug 402 fits into the opening in the neck rings with a slight clearance (such as .002") to permit a vacuum to be drawn on the glass charge. The upper part of the plug 402 forms the inside of the finish of the bottle from which the blowback is started. This plunger is adapted to reciprocate between the positions it occupies in Fig. 33 and Fig. 41.

There are two neck rings 408 and 409, one being attached to each of the mold halves 254 and 255. As shown in Figs. 33 and 35, each mold half is provided with 45 a suitable recess into which its corresponding neck ring section may be fitted and may be held by suitable headed screws 410. Preferably, the neck ring halves are slightly loose, so that they may adjust themselves when the mold halves are closed.

Each mold section is provided on its bottom with an arcuate groove 415 (Fig. 37), from which a plurality of holes 416 extend upwardly a distance at least sufficient to bring these holes to the top of the neck rings. These holes are arranged in an arc, the diameter of which is approximately equal to that of the neck ring sections, so that, as shown in Fig. 35, the holes 416 constitute a plurality of vertical grooves at the outer surfaces of the neck ring sections when the latter are in place. It will also be seen that the arcuate grooves register with the tops of the openings 396 in the head 395. The top surface of each neck ring section has a sloping recess 420 therein, as appears in Figs. 39 and 40. This may be considered as a tapered upper surface with teeth-like protuberances 421 around the rim thereof. These teeth-like protuberances are designed to insure an air passage from the vertical passages 416 across the top of the neck ring sections. Reference to Figs. 39 and 40 will show that the conical surface at the center bore of the neck rings terminates at 422, a slight distance below the upper surface of the neck rings themselves. This provides a communication space 423 between the neck ring sections and the adjacent walls of the recesses of the mold sections into which the neck rings are fitted, so that, as shown in Fig. 33, there may be a vacuum drawn onto the parison at the top of the neck rings.

75 In view of the fact that the vertical passages 416 open

into the neck ring recesses and are spaced differently from the spacing of the notches between the teeth 421 on the tops of the neck rings, communication across the sloping upper surfaces 420 of the neck rings is also assured.

The finish portions of the mold are adapted to receive both the application of vacuum and the application of pressure. The air flow to the finish portion of the mold takes place through the interior passages of the composite plunger.

Thus it is evident that the passages 403 in the top of the plunger adjacent the finish pin 402 communicate with the interior of the extension 381 of the plunger, which has the opening 425 therethrough. This opening 425, in turn, registers with a bore 426 that extends downwardly from the top of the piston rod 345, as shown in the drawings. At its bottom, as shown in Fig. 26, the bore 426 has a radial passage 428 that terminates in a peripheral groove 429 extending around the piston rod.

The bracket 330, as shown in Fig. 26, has a boss 430 extending between the conical upstanding sleeve 336 and the outer wall. This boss has a passage 431 therein that is adapted to register with the peripheral groove 429 in the piston rod 345. It is also adapted to be connected to an air line 432.

The line 432, Figs. 20, 23, 26 and 27, extends around to a valve housing 435 that is formed as part of the plate 341 that closes the bottom of the cylinder 340. This valve housing has an axial bore 437 extending therethrough from top to bottom, the top part 438 being enlarged to provide a valve seat 439. A valve member 440 is adapted to rest upon this seat, and is urged thereupon by a coil spring 441 that is confined at its upper end by a threaded plug 442. The valve 440 preferably is of the shape shown in Fig. 27, so as to hold the coil spring in place. Below the valve head, there is a stem 444 that passes down through a narrow part of the bore 437 and projects out the bottom thereof, as shown particularly in Figs. 23 and 27. The stem is preferably grooved to permit exhaust from the line 432 when the valve is closed. This groove terminates just below the housing 435 when the valve is closed, and is itself cut off when the valve is raised to open position.

It will be seen that above the valve 440 there is a connection 445 that is adapted to be connected to an air line, as will appear.

The stem 444, which is normally urged downwardly by the coil spring 441, is adapted to be engaged by one end 447 of a rocker arm 448 that is pivotally secured at 449 to a depending panel 450 that projects from the bottom of the plate 341. The extension 447 may engage a pin 451 that is located on the projecting panel 450 to limit the downward rocking movement of the rocker arm 448. This arm carries a cam roller 452 that is secured thereto, as by the screw 453.

It will be seen that, when the cam roller 452 is elevated, the rocker arm 448 is rocked, with the result that the valve 440 is opened and air may pass from the air line 445, past the valve 440, through the connecting line 432, and thence through the port 431, and, with the plunger down, thence through the peripheral groove 429 and the piston rod 345, and finally up through the bore 426 that extends axially upwardly in the composite piston rod. As shown in Fig. 41, this air then discharges upwardly through the ports 403 and into the glass to produce the counterblow.

The vacuum connections for the finish portion of the mold are made from the chamber 335 in the support bracket 330, and thence through the passages 392 above the chamber 335, the interior of the spacer sleeve 383, through the passages 396 and the holes 416, to the space above the neck rings, and also through the grooves 400, to the bottom of the finish, as previously described.

Also, when the piston is in its upper position, the bore in the piston rod is opened to the chamber 335. As shown

particularly in Fig. 33, there are a plurality of radial passages 460 that extend outwardly from the bore 426 extending downwardly into the piston rod 345. When the piston rod is down, as shown in Fig. 41, these radial passages are sealed against the portion 336 of the casting 330. However, when the piston rod is elevated and approaches its upper position, as shown in Fig. 33, these radial passages establish communication between the piston rod bore and the vacuum chamber 335.

The bracket 330 is rigidly attached at the back of its depending part, below the table 190, to a hollow valve chamber or housing 465 that is secured by means, such as the screws 464, to the underside of the rotating table 190. It is also held by screws 466 to the depending portion of the casting 330. The bracket 330 has a slight projection around the outlet of the passage 337 that is received in a complementary groove in the valve housing 465. These parts thereby mutually locate each other on the table, and together form, with the other parts previously described, a rigid vacuum connection between the table and the mold.

The housing 465 has an inlet 467 registering with the passage 337. It has an outlet 468 that is in registry with the port 210 leading from the annular vacuum chamber 196 in the rotating table 190. Between these two passages 467 and 468, there is a valve partition 469 that is adapted to receive the end of a valve member. This valve member is an assembly of valve seat and valve head with an operating means that may be inserted from the bottom of the housing 465. To this end, there is an opening 470 in the partition and immediately below it another opening 471 in the bottom wall of the casting 465. A valve assembly support member 472 has an extension 473 that fits upwardly through the two openings 470 and 471 and may be sealed therein. This assembly support 472 is attached to the housing 465 by screws 474.

The upstanding portion 473 of the valve assembly member 472 provides a valve seat 475 just above the partition 469. Below this valve seat, there is a bore providing a valve outlet chamber 476 that registers with an outlet 477 that opens into the passage 468.

A valve 478 controls the flow around the valve seat 475. This valve member 478 is urged by a spring 479 downwardly into seating position. However, it is mounted upon a valve stem 480 that extends downwardly through the valve assembly member 472 and has a yoke at the bottom to hold a cam wheel 481. This cam wheel may be elevated by a cam to open the valve. The valve 478 is shown open in Fig. 33 and closed in Fig. 41.

Blank mold baffles, and cooling air conductors

Arranged around the rotating table 190 are a plurality of wind or cooling air columns 490 (Figs. 18, 20, 83) that interfere with the openings 208 in the top of the rotating table. The columns 490 are hollow and are adapted to receive air under pressure from the air supply spaces within the table. These wind columns are held to the table by suitable screws.

There are a plurality of baffles for the tops of the blank or parison molds that are supported upon the table 190. These include cantilever supporting arms 492 (Figs. 5, 20 and 31). Each arm 492 is held by screws to the top of the table 190 adjacent the periphery thereof. As shown in Fig. 5 (Sheet 1), these arms are likewise held by screws to the column 490, so that these parts afford mutual aid in their support on the table. The radially inward ends of the arms 492 meet outwardly extending discharge passageway walls 493 that extend outwardly from the column. The arms 492 are hollow adjacent their inner ends, so as to provide wind passages 495 (Fig. 83) that communicate with the interior of the columns 490.

These wind passages 495 open to the tops of the arms 492 and are covered by a wind nozzle arrangement. This latter comprises a lower nozzle 496, an intermediate ring

497, and an upper nozzle 498 with a cap 499 over the top of the last. The upper and lower rings are substantially the same, and, by reference to Figs. 83 and 88-91, it will be seen that each of these rings has two nozzles 500 and 501 that direct air outwardly at angles. A damper 502, adjustable in a groove 503 in the bottom of the nozzle 497, may be employed for adjusting the amount of air that flows to the nozzles 496 and 498. These nozzles are directed toward the adjacent blank mold sections. For example, the nozzles adjacent the column 498 will tend to cool the mold sections 254a and 255b.

Each of the arms 492 extends outwardly in an arcuate manner, as shown for example in Fig. 20, and terminates at its outer end in a head 509 having a vertical circular opening 510 therethrough (Fig. 31). The opening 510 receives a somewhat smaller depending sleeve 511 of a cam track member 512, there being a flange 513 that rests upon the top of the arm 492. Below the head 509 of the arm, there is a cylinder 514 that is flanged at 515, and which closely interfits with the sleeve 511 to provide a seal. The head 509 of the arms is of generally square shape, as shown in Fig. 20. Four screws 516 pass upwardly through somewhat enlarged holes in the corners of the head 509 and hold the cylinder 514, the head 509, and the upper casting 512 together. Additionally, setscrews 517 pass through the wall of the head 509 and engage the sleeve 511. The screws 516 may be loosened, after which the screws 517 may be operated in proper combination to give alignment to the baffle plate mounting on the head. Then the screws 516 may be re-tightened to hold the adjustment.

The cylinder 514 is closed by a cylinder head 518, into which an air line 519 leads. The cylinder contains a piston 520, having a piston rod 521 that extends upwardly through a bushing in the sleeve 511. It also extends out the top of the casting 512, and, at its outer end, supports a baffle head supporting arm 523. These arms 523 are shown in greater detail in Figs. 42 and 43. It will be seen that each arm is clamped to its shaft 521 by a clamping block 525, a screw 526 and a bolt 527.

The outer end of the arm 523 has a head 528 thereon with a vertical threaded opening 529 therethrough. This opening receives the threaded baffle head rod 530, kerfed at its top. It receives a clamp nut 531 that is threaded onto the shaft 530 above the head 528. It also receives a clamping bracket 532 that is held by a screw 533 in a boss 534 rising from the top of the arm 523. The clamp 532 is in the form of a split collar and may be tightened around the shaft 530 by a screw 535. In use, the ring clamp 532 is always held yieldably tightly on the screw 530. The ring 531 may be loosened, after which the screw may be turned in very small increments by a tool inserted in the kerf, and will hold such adjustment. The collar 531 may then be tightened firmly. This arrangement makes possible such fine adjustments as the accurate alignment of baffle plates for oval bottles.

The shaft 530 is designed to support a disc or plate 537 in the manner shown in Fig. 41. This plate has two opposite holes 538 therethrough that are designed to receive pins 539 on a baffle plate 540. The holes are slightly larger than the pins. The baffle plates are shaped to interfit with recesses 542 at the tops of the mold sections with a self-sealing, wedging action. A spring 541, as shown in Fig. 44, is adapted to interfit with necks on the two pins 539 to hold the baffle plates onto the support means. The arrangement permits a certain amount of movement of the baffle plates 540 so that they may center themselves and seal properly in the top of the mold sections. It is apparent that this arrangement permits great flexibility for the use of the proper baffle plates for particular molds.

The means for displacing the baffle plates from the position in station *a* of Fig. 1 to the position of station *b* comprises mechanism for raising and lowering and

twisting the vertical shaft 521 that supports each of the arms 523 and the corresponding baffle plate. To this end, the casting 512, as shown in Figs. 31 and 32, has an opening 543 on one side, through which a cam roller and its clamp may be inserted. The cam roller is shown at 544, and it is adapted to fit in a more or less spiral cam slot 545, having a vertical bottom end, in the casting 512. The cam roller 544 is rotatably mounted on a first clamp member 546, to which a second clamp member 547 is held by screws, as shown in Fig. 32, and both are held by a lock screw, as shown in Fig. 32, to the shaft 521.

It may be seen that, when the piston 520 is caused to move downwardly, the baffle head will be lowered, and the cam roller 544, operating in the cam slot 545, will also cause the shaft 521 to twist, moving the baffle head laterally to the top of the mold. The final seating movement is wholly vertical, as the bottom of the cam slot 545 is vertical. When the piston 520 moves upwardly, the shaft 521 will elevate and twist. As is evident, this vertical and rotary movement is imparted to the baffle plates 540, so that they can move in the manner shown in Fig. 18, and which will be described in more detail hereafter.

The operation of the piston 520 is determined by a valve shown in Figs. 20 and 29. This valve includes a valve housing 550 with a horizontal supporting plate 551 extending therefrom and held by screws to the bottom of the rotating table 190. This valve housing 550 has a vertical bore extending through it. This bore is closed at the top by a cap 552 that is bolted to the housing. This cap receives an air inlet line 553. The housing 550 likewise has two radial air ports into which the air lines 555 and 556, respectively, are connected. These air lines 555 and 556 are connected into the bottom and top, respectively, of the cylinder 514. Additionally, the valve housing has exhaust ports 557 and 558 that discharge into atmosphere or any suitable exhaust lines.

The air flow through the valve 550 is controlled by a slide valve 560 that has a central bore 561 extending downwardly from the top thereof. At the bottom of this bore, there is a radial opening 562, and about the middle of the bore is another radial opening 563. Below the radial bore 562, there is a peripheral groove 564, and above the radial passage 563 there is another peripheral groove 565.

The valve sleeve 560 projects downwardly through the bottom of the housing 551 and is provided with a cam roller 566 at its bottom end. It is prevented from rotation by means of a roller 567 (Figs. 29 and 30) that is rotatably supported on the sleeve 560 and is engageable in the slot 568 in the housing 550. This roller and slot delimit the vertical movements of the valve.

It will be seen that, when the sleeve 560 is in its lowermost position, as shown in Fig. 29, the line 555 is connected to exhaust through the peripheral groove 565 and the exhaust line 557. At this time, the air supply from the intake into the cap 552 passes through the vertical bore 561 and out the radial passage 562 into the line 556.

It is also evident that, when the cam roller 566 lifts the sleeve, these conditions will be reversed, the line 555 being connected to the air source, the line 556 being connected to the exhaust 558.

Blank mold cam tracks

At the nine-o'clock position in the drawings, the gob is fed into the closed blank mold, the vacuum comes on and the plunger goes up. Also, the blank mold is, of course, securely closed at this point.

The vacuum is under control of the valve 478 (Fig. 33), which, in turn, is controlled by the cam roller 481. The operation of the plunger is controlled by the valve 348, which is regulated by the cam roller 355. A short time thereafter the baffle must close in preparation for the blowback or counterblow. This baffle operation is

controlled by the valve 550, which is, in turn, regulated by the cam roller 566. Finally, the counterblow is under control of the valve 440, which, in turn, is operated by the cam roller 452. The cam rollers 355, 481 and 566 are operated by a set of cam tracks shown in plan view in Figs. 6 and 11. These tracks are supported on a track base plate 575 that is held by screws onto the base 125 of the machine, as appears in Figs. 11-14.

The inner one of these tracks is for operating the vacuum valve 478 and consists of a main rail 576 that is generally arcuate in shape and that extends from somewhat ahead of the nine-o'clock position in the plan drawings to beyond the nine-o'clock position. This rail 576 is duly held onto tie plates 577 and 578, as by welding, or the like. These plates are held by screws, as shown in Fig. 13 for example, to upstanding bosses on the base plate 575.

There are a pair of supplementary rails 579 and 580 that are disposed adjacent the ends of the main rail 576, whereby the length of this main rail may be changed in either direction. Referring particularly to the supplemental rail 580, it may be seen from Fig. 11 that this rail is held to the main rail 576 by a pair of bolts 581 and 582 that are fairly closely fitted into the principal rails 576 but fit in slots 583 in the supplemental rails. These slots 583 extend lengthwise of the supplemental rails. By this means, as is evident, the supplemental rails are supported against the main rails but may be slid longitudinally of the main rails.

Means is provided for readily moving the supplemental rails in the manner aforesaid, the means being accessible from the side of the machine. Referring particularly to the supplemental rail 580, this adjusting means includes a bell crank arm 585 pivoted at 586 to the base plate 575. One end of the bell crank arm is bifurcated at 587 to receive a pin 588 projecting from the lower edge of the supplemental rail 580. The other end of the bell crank is pivoted at 589 to a rod 590. The rod 590 extends outwardly past a notched flange 591 on the edge of the plate 575. A nut 592 is threaded over the end of the rod 590; and this nut has a neck portion 593 that fits into the notch of the flanged part 591. As a result of this arrangement, when the nut 592 is rotated, it is held against axial movement and the rod 590 is axially displaced. This rocks the bell crank 585 and ultimately shifts the supplemental rail 580 longitudinally.

In like manner, the other rail 579 is engaged by a bell crank 595 that is pivoted at 596 to the plate 575. Its other end is connected with a threaded rod 597 that may be regulated by a nut 598 that engages within the bifurcations 599 of the flange. Thus, turning the thumb nut 598 adjusts the start of the vacuum pulldown, and turning the thumb nut 592 adjusts the ending thereof.

The plunger-controlling cam roller 355 is operated by the outer track, which consists of a main rail 603 secured by plates 604 and 605 to the main cam track plate 575. Supplemental rails 605 and 606, at the counterclockwise (starting) and clockwise (ending) ends of the main rail 603, are longitudinally adjustably secured to the main rail 603, as by bolts 607 and 608 that operate in slots, as is self-evident. Adjusting means are provided for the supplemental rail 605 in the form of a bell crank 609 that is operated by a turn nut 610, similar to the previously mentioned adjusting means. This collar fits within two upstanding projections on the flange of the base plate. In like manner, the supplemental rail 606 is adjusted by a bell crank lever 612 that is operated by a nut 613.

It will be evident that the bolts of these various tracks may be held sufficiently tightly to prevent accidental displacement of the rails, but loosely enough to permit them to be longitudinally adjusted by the various nuts.

The cam track 615, that operates the baffle plate, is composed of a plurality of main rail strips with supplemental end rails, as shown in Figs. 6 and 11. The main

5

rails, reading clockwise, are designated 616, 617, and 618, they being bolted, welded, or otherwise secured together at their ends. These several strips are mounted on plates 620, 621, 622 and 575 that are attached to the base of the machine.

There is a supplementary rail 623 adjustably attached to the starting end of the track 616 by bolts 624 secured through one rail and engaging in slots in the other, as in the case of other supplemental tracks.

10 At the terminal end of this track 615, there is another supplemental end rail 626, held by bolts 628 and 629 to the rail 618, and having the previous slot arrangement providing for endwise adjustment of the supplemental rail 623. No specific manual adjusting screws are shown 15 for these rails.

20 The blowback or counterblow valve 440, which is controlled by the roller 452, admits air under pressure to the mold when the roller 452 rises. This roller is designed to cooperate with a track, generally indicated at 635 (Fig. 6). This track is made of a plurality of strips that are secured to the base or to the extension 233 by suitable plates 636, 637, 638 and 639. There is a supplemental rail at each end of the main rail. At the starting end, the supplemental rail is indicated at 640, it being adjustable along the main rail by screws 641 that engage through slots in the rail 640 and are threaded into the main rail. The supplemental rail at the other end is shown at 642, and it is likewise slidably along the main rail on screws 643 passing through slots in the supplemental rail and threaded into the main rail 635.

25 The air pressure valve is adapted to be opened also, in addition to its counterblowing, in order to clear the blank molds of excess lubricant residing therein as a result of spraying the interior of the mold prior to introducing a fresh gob of glass therein. To this end, at approximately the seven o'clock position in Fig. 6, there is a rail 644 supported on a bracket 645 that is attached to the base 125. When the valve 440 is opened at this time, a stream of air is directed onto the open blank mold 40 sections.

Vacuum

30 As heretofore noted, there is an annular chamber 196 within the rotating table 190 that is a vacuum chamber. To it are connected the various passages 468 that are 45 valved by the valves 478 to the passages 337 that are connected to the lower parts of the mold to draw the vacuum on the glass within the mold for the finish pull-down. It will also appear hereafter that the annular 50 vacuum chamber 196 in the rotating table 190 is connected to the transfer mechanism.

55 As shown in Fig. 18 (Sheet 6), there are two diametrically opposite vacuum connections leading down into the top of the rotating table 190. These include the two pipes 665 and 666, both having identical fittings 667 and 668, respectively, connecting into the top of the vacuum chamber 196.

60 As shown in Fig. 16 (Sheet 5), the pipes 665 and 666 connect into the opposite sides of an annular rotating vacuum chamber 669. This chamber 669 has a box-shaped cross section, as shown in Figs. 2 and 3. It is adapted to rotate upon a stationary member 670 secured by setscrews 671 to the wall 144 of the lower column member.

65 The member 669 is caused to rotate upon the stationary member 670 by having a connection with the table 190. As shown in Fig. 2, there are two socket members 672 held by screws to the top of the table 190 on opposite sides of the center column. These receive vertical posts or pins 673. These pins pass through ears 675 that are formed integral with and extend laterally from the member 669. Above the ears, coil springs 677 surround the posts 673, and are held by caps screwed into the top of the pins, as is evident from the drawings. It will be understood that the pins are securely held into the socket

members 672. Consequently, the springs 677 exert a downward force upon the members 669, causing its lower surface to seal tightly against the horizontal surface on the member 670.

The housing 669 has a plurality of arcuate openings 679 in the bottom thereof. The stationary member 670 has a plurality of ports 680 in its horizontal surface. These ports communicate through the ports 153 in the column member, with the vacuum chamber 151. The arcuate openings 679 are of such length that they will register with any two adjacent ports 680 in the horizontal surface of the member 670. As appears in Fig. 16, it is thus impossible to cut off the flow of air from the chamber 669 into the vacuum chamber 151 at any point in the rotation of the housing 669. Yet a good seal, eliminating pressure loss, is obtained.

The compressed air supply and its course through the machine will be described hereafter.

Transfer devices

Next above the blank mold mechanisms are the transfer devices. Each transfer mechanism has a base casting 685, mounted between adjacent wind columns 490. The base casting 685 has two lateral projections 686 and 687 (Fig. 48) that are adapted to rest upon and be supported by the flanges 688 on the adjacent columns 490. It is also apparent that each lateral extension 686 and 687 is disposed largely at its near side of its column 490. The columns are provided with circular ridges 690 at their corners around the flanges. The lateral extensions are shaped to fit accurately around the outer arcuate surfaces of these ridges, for easy positioning of the transfer devices, and for holding them in place, as the extensions cannot be pulled out when so engaged. A transfer mechanism may be easily removed by lifting it over the ridges and then drawing it outwardly. As is shown, the flanges 688 are rectangular in shape, so as to receive the lateral projections 686 and 687 and provide space for screws or bolts 691.

At the inner ends of each support casting 685, there is mounted a cylinder 692. The upper surface of the casting 685 may preferably be provided with longitudinal ridges that interfit with a complementary shaped bottom on the cylinder 692 to provide lateral positioning of the cylinder. Additionally, the cylinder and the adjacent upper surface of the casting 685 are provided with transverse grooves to receive a key 693 that properly positions the cylinder lengthwise of the casting. By this means, the parts may be interfitted together in the most simple way. The cylinder is held to the casting by screws that pass upwardly through the bottom of the casting.

The cylinder 692 contains a piston 694 (Fig. 47) reciprocable therein, this piston having a piston rod 695 that passes outwardly through a cylinder head 696 secured by screws 697 to the cylinder. This cylinder head has three horizontally disposed bosses, including a central boss 698 and two lateral bosses 700 projecting therefrom. The central boss 698 has a threaded projection thereon, over which a stuffing box nut 701 is threaded. The piston rod 695 passes through the central bosses and the stuffing nut to project radially outwardly over the top of the support casting 685. Its outer end is given flat vertical sides that fit in a slot in a crosshead 702, to which it is held, inward of its extreme end, by a pin 703.

The crosshead 702 comprises a base member 705 in the form of a slide plate resting slidably upon the upper surface of the support 685. Two side members 706 stand up from the base 705 on opposite sides of the piston rod.

The base plate 705 of the crosshead 702 is confined by two sides 708 that stand upwardly from the base casting 685. Across the top of each of the two sides 708 is a jib 709 that is held thereto by screws 710 that pass down through curved enlargements in the side members. The jibs 709 project inwardly beyond the upper edges of the walls 708, and engage the top edges of the slide plate

705 of the crosshead slide member and confine it to the proper sliding movement.

The members 706 are also arranged to comprise split threaded collars that receive impact spring adjusting screws 711. They may be threaded into or out of the openings through the wings 706 and secured in adjusted position by the tightening of the clamp screws 713.

Each of the screws 711 receives a spring rod 715. These rods may pass freely through the two screws and are anchored in the two bosses 700 on the cylinder head, being secured by the screws 717. A pair of coil springs 719 are engaged around the two rods, and preferably are secured to the bosses 700. It will be seen that, when the piston moves backwardly to the position shown in Fig. 47 from the position shown in Fig. 51, the two screws 711 will engage the outer ends of the two coil springs 719 to compress the same, this cushioning and decelerating the end of this stroke of the piston.

The movement of the piston in this direction is adjustably controlled by an abutment means 723 in the form of a screw that is engaged through the closed inner end of the cylinder 692. This screw 723 may be adjusted by the head thereon, as shown, and secured in adjusted position by a lock nut 724. Also, it will be evident that the point 20 wherein the two sleeves 711 engage the cushioning springs 719 is determined by the adjustment of the two sleeves in the wings 706 and 707. This regulates the force of the cushioning springs.

The flat end of the piston rod 694 is also connected 30 to a yoke 725 by a pivot pin 726. The threaded shank of the yoke 725 engages a turnbuckle sleeve nut 727, into which it may be adjusted. This nut 727 also receives a threaded shank of a connecting rod 728 that is pivotally mounted at 729 between crank arm bosses 730 on a complex casting 731, shown separately in Figs. 51 and 52, that has the general nature of a bell crank lever. It has what may be called central bearings 732 adapted to receive a wrist pin 733 (Fig. 56), which wrist pin is supported in spaced bearings 734 that are formed in the side 35 walls of the outer end of the main supporting casting 685.

The other arm of the casting 731 extends out at 738 at an angle laterally of the radial axis of the machine, and it has a transverse sleeve portion 739 at its outer end. This sleeve has two portions separated by a flange 740, an arrangement affording a bearing surface 741 for the support of a swinging head 742. This head 742 has a flat bottom and an arched top, as viewed in Figs. 48 and 49. It appears in section in Fig. 55, and in a broken section in Fig. 53. This head has a bore all the way through it. 40 The bore includes an enlarged section 744 that receives the projecting end of the head 739 in the bearing surface 741 so that the head 742 is rotatably supported on the sleeve 739. The bore also has a reduced portion 745, that receives the larger end 746 of a spindle, generally indicated at 747.

This spindle has a reduced intermediate section 748 and an enlarged opposite end 749. It has an integral flange 750 that limits its movement through the parts previously described. The right hand end (Fig. 55) of the spindle 60 746 receives an adjustment-holding dog member 753, keyed at 754 (Fig. 50) to rotate with the shaft 746, and having a dog element 755 projecting upwardly therefrom between two spaced ears 756 that project outwardly from the upper part of the right end of the transfer swinging head 742. These ears 756 receive adjusting screws 758, duly provided with lock nuts and engageable with the opposite sides of the dog 755. By this means, a close and secure angular adjustment of the transfer head may be made. The dog member is held against removal from the shaft by a suitable nut 760 that engages over a reduced threaded end of the spindle 747. This nut also confines the transfer swinging head against removal from the sleeve end 739 on the bell crank member 731, but permits rotation thereof.

75 As shown in Fig. 49, for example, the transfer swinging

head 742 has outwardly extending ears 763 that receive the spring lock pins 765 (Figs. 78-79, Sheet 16). These pins have reduced threaded ends to which washer and nut arrangements 766 are attached so as to confine coil springs 767. The pins pass through the ears 763 and have tapering flanges 768 thereon, which tapering flanges may seat in recesses within the ears 763. Beyond the flanges 768, the pins continue with more or less reduced diameters to enlarged end heads 769. As shown in Fig. 79, these heads 769 are adapted to engage in slots 770 in ears 771 in a transfer vacuum head, generally indicated at 775. It will be seen that the ears 771 have depressions 776 to receive the tapered heads 769 when the vacuum head is turned so as to be fully engaged over the pins. This means that the heads 769 are forced upwardly in the initial engagement of the heads in the slots 770, thus compressing the springs 767 until the heads may snap into the depressions 776 when the parts are fully engaged. The spacing between the several heads and recesses is sufficient to permit the foregoing operation to take place.

The vacuum heads 775 are provided with outer ends that are tapered and shaped as at 780 to interfit both with the recesses 542 in the top of the blank mold sections, with which the heads 540 of the baffle plates also interfit, and with complementary grooves in finish mold sections as will appear hereinafter. These vacuum heads are hollow, having an enlarged passage 781 therethrough that terminates in a plurality of small passages 782 that extend through the end of the head, while at the same time permitting the provision of a bottom plate that conforms to the shape of the bottom of the glassware to be produced.

The opposite end of each vacuum head has a projection 783 thereon that is adapted to interfit with a slight indentation in the surface of the member 742. The projection 783 is slightly smaller than this recess, this permitting a certain amount of self-centering of the parts. In other words, when the vacuum head is inserted into the recess in the mold, it will seat tightly because it may move slightly relative to the transfer head. Such relative movement is accommodated by the fact that the two diameters of the pins 765 are slightly smaller than the two diameters of the holes through which they fit, and also because of the slightly smaller size of the projection 783. The conical surfaces on the pins 765 cause them to secure a tight holding action. The interfaces between the vacuum head and the transfer swinging head are machined so as to provide surfaces that will not permit the leakage of air.

From the foregoing it may be seen that, when the connecting rod 695 is drawn back from the position shown in Figs. 48 and 49, it will pull on the upper arm 730 of the bell crank 731, rocking the bell crank about its pin 733 and causing it to move to the positions shown in Figs. 2 and 78. It will appear later that, in this action, it transfers the parison or blank from the blank mold to the finish mold.

As will appear, it is necessary for the vacuum head to rock approximately 90° relative to the arm 738 of the bell crank member 731, when it moves from the position of Fig. 49 to the position of Fig. 78. This is accomplished by means of a rocking link arrangement. This rocking link arrangement comprises a transfer roller bracket 787 that is held by screws to one of the lateral projections 686 on the support casing 685. The end of the bracket 787 has a journal bearing 788 that receives a stud 789, this stud being designed to provide a free bearing that fits within a slot 790 on a swinging head crank 791. The other end of this crank has a circular opening that fits over a reduced end 792 of the swinging head spindle 747 (Fig. 55). The crank 791 is keyed to the spindle and is secured thereto by a suitable screw and washer arrangement 793. As shown above in column 22, the spindle 747 is secured to the head 742 to cause the two to rotate together. Such securing is obtained by the keying

of the spindle 747 to the dog member 753 by the key 754, and the disposition of the dog element 755 between the screws 758 on the ears 756 that are part of the head 742.

By this mechanism, it will be seen that, when the head is moved from the position shown in full lines in Fig. 49 to the position shown in dotted lines, by the rocking of the bell crank 731 about its journal pin 733, the head will change its relative position so that, when it reaches the dotted line position (cf. Fig. 78), it faces vertically upwardly instead of vertically downward. This may be understood by observing that the movement of the head 742 has two controls. It rocks arcuately in space about the axis of the shaft 733 and it swings about its own axis, the center of the shaft 747. In other words, the head spindle 747 moves arcuately in space about the axis 733, and rocks around its own axis. The angle between the head crank 791 and the head 742 is constant. The head crank 791, representing one side of this constant angle, must always pass through the center of the journal 789.

Since the axis of the spindle 747 moves in a 90° arc, the axis of the journal 789 is fixed, the angle between the head 742 and the head crank 791 is constant, and the center or axis 789 is contained within the angle of rocking 25 of the head 742 about its fixed axis 733, the total rocking of the head will be a function of the disposition of the axis 789 with respect to a chord of the arc of movement of the head about its fixed axis 733. Since here the axis 789 is on the chord, the total swinging of the head is 30 180°.

This transfer mechanism operates on the vacuum principle. This vacuum is derived from the vacuum chamber 196 of the rotating table 190. As shown in Figs. 20 and 21, there are a plurality of openings through the top of 35 this vacuum chamber 196, one for each mold set. Each opening receives a pipe fitting including an elbow, generally indicated at 800. Piping 801 leads from each fitting.

Flow from the vacuum chamber 196 to the fitting 800 40 in the piping 801 is controlled by a valve. To this end, a cylindrical valve housing 802 in the form of a sleeve is inserted upwardly from the bottom of the table 190. It has a flange 803 that limits its upward movement and receives attaching bolts. Each fitting 800 likewise has such extensions 805, and bolts 806 may pass through the extensions 803 and the extensions 805 to hold these parts onto the table.

Each valve housing 802 projects through the top of 50 the table 190 and provides a valve seat 806 at its upper end. Within the vacuum chamber 196, the sleeve is ported as at 807, and below the port 807 is a partition 808.

There is a valve 809 adapted to engage the seat 806. It is secured to a stem 810 that passes downwardly through the partition 808 and has a head 811 at its lower end, this head being slidably received within the lower part of the sleeve 802.

As is evident, the valve stem 810 is held to the valve head 809 by a nut. A coil spring 812 fits over the valve stem below the partition 808, so as to urge the valve toward seating position.

The head 811 projects below the sleeve 802 to support a cam roller 813. There is a pin 814 that is secured to the cylinder 802 and passes through the same, also passing through a slot 815 in the head 811. This slot prevents rotation of the valve and of the head, and also determines the maximum upward movement thereof.

The cam roller 813 is designed to be engaged with a cam track 818 (Figs. 6, 8 and 9). The track 818 is a composite including a main stationary rail 819, duly supported on the plates 622, 621 and 624. At the clockwise end thereof in Fig. 6, there is a first supplemental movable rail 821. This rail has two ears 822 and 823 projecting laterally below the same and adapted to receive a turn screw 824, having a threaded end. This turn screw extends outwardly from the bottom of the machine and

has a knurled turning wheel 825 at its end. The turn screw has set thereon a collar 826 that is disposed between the two ears 822 and 823. The turn screw is threadedly engaged in a lug 827 that is formed as an upstanding part of the plate 624. It will be seen that, when the screw 824 is turned, it will move axially with respect to the fixed plate 624 by its threaded engagement through the boss 827 upstanding therefrom. This will cause the collar 826 to engage one or the other of the two ears 822 and 823 and displace the supplemental rail 821 along the fixed rail 819. Suitable bolts, such as the bolt 828, operable in slots 829 may be provided to hold the rails together.

At the other end of the fixed rail 819, there is a supplemental rail 830 adjustably secured thereto as by bolts that engage through slots similar to the arrangement for the rail 635, so that it may be adjusted to determine the end point of the cam ride on the composite rail.

The vacuum piping 801 from the valve 802, controlled by the track 818, extends upwardly and is connected into a bore 835 within the pin 733, on which the bell crank member 731 rocks (Figs. 48, 56). The bore 835 has a plurality of radially disposed ports 836 that are disposed midway between the length of the pin 733 and midway of the length of the rocking portion 732 of the bell crank head 731. This portion 732 is provided with a vacuum channel 837 therearound. As shown, for example in Fig. 51, this channel 837 passes up the angular arm 738 and opens into the sleeve 739 adjacent the reduced portion 748 of the spindle 747. From thence, it may extend to the right end (Fig. 55) of the sleeve 739. At this location, there are a plurality of radial ports 840 that open out into a channel 841 that extends around the projection 741 of the sleeve 739 within the swinging head 742, so as to insure a communication between the passage 781 within the vacuum head and the foregoing passages. Thus, vacuum will be drawn through the plurality of small ports 782, that, as will ultimately appear, are brought up against the bottom of the ware being produced.

The transfer mechanism is shifted by movement of the piston 694. This piston is controlled by a valve, generally indicated at 850 (Fig. 47). This valve includes a valve housing 851 that is held by screws to the top of the cylinder 692. This valve is provided with an interfitting channel surface engaging over a corresponding surface on the top of the cylinder, and there is a key 852 interfitting in keyways in the cylinder of the valve housing. This arrangement provides for ready interfitting of the parts and complete accuracy in their disposition.

The valve housing 850 has an inlet 855 that is adapted to receive air under pressure. This inlet fits through a head 856 that is held by screws onto the end of the housing. Within the housing, there is a valve slide or plug 857 that has a central bore 858 down through the same. This bore is provided with a radial passage 859 toward one end and a second radial passage 860 toward its other end. It is also provided with peripheral grooves 861 and 862.

The valve housing is provided with radial passages 863 and 864. These are adapted to register with passages 865 and 866 that lead, respectively, to the ends of the cylinder 692 on opposite sides of the piston 694. Also, the housing has exhaust ports 867 and 868.

The valve plug 857 extends outwardly through the housing and has a cam roller 869 at the end thereof. It also has a guide roller arrangement 870 that engages within a slot 871 on an arm formed laterally on the valve housing 851. This roller and slot arrangement determines the maximum movement of the valve, and also prevents it from rotating.

It will be seen that, when the valve is in the position shown in Fig. 47, air may flow through the axial passage 858 and the radial passage 860, to the passages 864 and 866, to the right hand side of the piston 694, so that the same is forced to the left the maximum distance, as is shown. In the meanwhile, the left side of the piston is

ported to exhaust by the passages 865, 863 to the groove 861, which establishes communication with the exhaust outlet 867.

The air pressure normally urges the valve into the position shown. However, when the roller 869 is caused by its cam to move to the right in Fig. 47, it will reverse the action by reversing the air and exhaust connections as is evident. This will cause the piston to move in the opposite direction. In so doing, it will move the vacuum head from the dotted line position of Fig. 49 to the full line position, as will be described in more detail hereafter.

Transfer operating valve cam

The cam roller 869, and consequently the valve mechanism 850, are operated by a composite cam mechanism supported on the central column. This cam mechanism is shown in detail in Figs. 57 to 63 (Sheet 13).

As shown in Figs. 2 and 3, there is a sleeve or center collar for this adjustable cam, indicated at 875, and supported upon the section 167 of the central column. This collar is fixed to the column by a setscrew 876. It has an upper flange, a lower flange, and two projecting ears 877 and 878.

Supported upon the collar and resting upon its lower flange is a lower cam track ring 879 that is formed of two semi-circular portions that may be secured together by bolts 880, as shown in Fig. 60. By this means, this cam track ring may be mounted around the collar. It fits closely thereon but is oscillatable on the collar. This cam track ring 879 has a cylindrical boss 881 upstanding from the flange thereof. One of the sections of the ring has a slot portion 882, for a purpose that will appear hereafter. The other ring section has a ledge, generally indicated at 883, it having an arcuate vertical back wall 884 and also having a plurality of screw holes 885. This ledge 883 stands up somewhat from the principal flange of the ring section, as appears in Fig. 58.

A lower cam track member 886 is shown in Fig. 63 as having a plurality of screw holes 887 that are spaced to receive screws that pass into the holes 885 on the ledge 883. This track member 886 has a tapering end 888, which constitutes the release end for the cam roller, as will appear. This cam track member is thus screwed over the top of the ledge 883, and, when so positioned, it comes to the top of the lower cam track ring member 879, as appears in Fig. 58.

The cylindrical boss 881 on the lower cam track ring is adapted to receive a threaded end 890 on a cylindrical stud 891, which stud 891 may be held to the boss 881 by a nut 892, as shown in Fig. 58. The main cylindrical portion of the stud 891 has a length sufficient to dispose the top of the stud at a point slightly below the flange on the collar 875. It receives in its top a bushing 893 and a screw 894, both of which secure a link 895 pivotally to the stud 891 and ultimately thereby to the lower cam track ring 879. The link 895, in turn, is pivotally connected at 896 to one head 897 of a crank 898. The other head 899 of the crank 898 has a square bore through it, which receives the squared end of a cam adjustment shaft 900. This shaft 900 has a lower rounded bearing end that engages in the opening of the ear 877 on the collar, and is thereby supported and guided.

From the foregoing, it will be seen that rotation of the shaft 900 turns the crank 898 and displaces the link 895 to draw the lower cam track ring around the collar, and thereby to adjust the cam track element 886 to determine the end point of the cam action. The shaft 900 extends to the top of the machine above the table 318, and has a gear 901 thereat, which is in mesh with a worm 902 of a shaft 903 supported on a bracket 904. The shaft 903 has an adjusting knob 905 at its outer end. By this arrangement, an operator can adjust the end of the cam action by rotating the knob 905.

Above the lower cam track ring 879 is an upper cam track ring 909, shown in Fig. 59 as comprising two ring

sections, held together by screws 910. One of the sections has a slot portion 911, for a purpose to be described. The other section has a cam element supporting ledge 912 that has a depending arcuate vertical flange 913. The ledge also has two holes 914 therein that are adapted to receive screws that pass through corresponding holes 915 of a cam track element 916 (Fig. 62). This cam element 916 is adapted to be screwed to the bottom surface of the ledge 912. The parts are so disposed that the ledge 912 is above the ledge 883 of the lower ring, and the cam element 916 is in sliding relation with the upper surface of the lower cam element 886. The element 916 has a tapered leading end 918 so as to receive the cam roller and cause the same to ride out onto the outer edge, as appears in Fig. 57.

The upper cam track ring is adjustable also. For this purpose, there is a cylindrical boss 920 upstanding from the top of the ledge 912. This is adapted to receive a bushing 921 and screw 922 that hold one end of a link 923. The other end of this link is pivoted at 924 to the arm 925 of a crank arm. The other end of the crank arm receives the squared end of a transfer shaft 928. The lower end of this shaft is engaged in the hole in the ear 878, so that the shaft is steadied and is borne thereby. The upper end of the shaft 928 projects outwardly from the top of the machine above the table 318, and has a gear 930 secured thereto, this gear being in mesh with the worm 931 fixed to a shaft 932 supported in a bracket 933. This shaft has an adjusting knob 934 at its outer end. It will be seen that the upper cam track ring may thus be adjusted, and that, when it is adjusted, it varies the point at which the beginning of the composite cam track is disposed. The two adjustments vary the length of the action and also the point in a total cycle at which it occurs.

The two slot sections 882 and 911 of the cam track rings are provided to receive the cam adjusting shaft 316, heretofore described. The slots are long enough to permit the cam parts to be adequately adjusted.

Blow mold

Each of the wind columns 490, that are mounted upon the rotating table 190, as shown in Fig. 83 (Sheet 17), has an upper ledge 940. The ledge 940 may be formed as a part of a circle. It is provided with a top hole 941, extending upwardly therethrough, and with a vertical circular flange 942 around the hole. The several flanges 942 are adapted to interfit with openings 943 around a blow mold hangar base ring 944 (see particularly Sheet 14). The foregoing obtains accurate location of the blow mold ring 944, as the columns 490 are already similarly engaged in the openings 208 in the table 190, which openings are accurate in size and position. A plurality of screw holes 945 may receive screws to hold these parts 944 and 490 together.

The ring 944 has a central opening 947 therein, this opening having a flange 948 standing upwardly therefrom. As there are ten of the columns 490, spaced equally around the rotating table 190, the blow mold hangar ring 944 is supported at ten points around its periphery. There are ten blow molds, corresponding to the ten blank molds. The ring rotates with the rotation of the table 190.

As shown in Figs. 2 and 3, the supporting ring 944 is adapted to receive a plurality of mold hinge pins and cylinder blocks 950 that are identical with the similar blocks 236 for the blank molds. They are shown in detail in Figs. 68-70. The earlier description of these blocks 236 renders repetition here unnecessary.

The finished portions 243 of the blocks 950 interfit with notches 960 spaced around the flange 948 of the base ring. The notches 960, shown particularly in Figs. 66 and 67, are sized and positioned properly to receive these finished positioning parts 243 of the blocks 950 and to position these parts against lateral movement. Additionally, as in the blank molds, each block receives a mold

hinge pin 962 in an opening 238 in the block 950, that fits with a hole 963 in the ring 944, that is the same as the interfit of the blank mold hinge pin 244 in the hole 209 in the rotating table 190. The pin 962 and the notch 960 provide complete and accurate positioning for the blocks 950 around the support ring.

The ring is the support for the blow mold sections 964 and 965, the blow molds generally being designated at 966. The blow mold section 964 is provided with hinge ears 967 that interfit with hinge ears 968 of the mold section 965, to support these mold halves on the pin or spindle 962. The pin 962 is threaded for a space at 969, and is pressed into the hole 238 down to the threads. About this threaded portion, there is a collar arrangement 970, corresponding to the collar 247 on the blank mold section, and by which the mold sections may be adjusted vertically and secured in adjusted position.

The two mold halves 964 and 965 are connected by links 971 and 972, respectively, to a yoke 973. This yoke is formed integrally with the end of a piston rod 976, to which a piston 977 is secured.

The piston reciprocates in a cylinder 978. This cylinder is in all respects identical with the cylinder 260 that operates the blank mold. It has, therefore, a guiding key 979 that properly positions it axially on the block 950, and it has lateral depending flanges 980 that fit over the sides of the overhanging part 242 of the block 950. The key and flanges fully locate the cylinder on the block. It is finally secured to the block by screws 981.

Each piston 977 is attached to its piston rod 976, as shown in Fig. 47. The pistons 977 fit over reduced and shouldered portions of the rods 976 and are secured by countersunk nuts 982. The piston rods project inwardly, as shown at 983, through journal bearings 984 in the cylinder heads 985, that are secured to the cylinders 978. These guide rods also reciprocate in caps 986 that are bolted to the cylinder heads 985.

The pistons are operated by valve mechanisms, generally indicated at 990, they being identical with the valve mechanisms for the blank molds that are generally indicated at 270. There is thus a valve housing 991 that engages with the pin 992 that corresponds with the pin 272. The valve housing is likewise flanged, as shown at 993, on its opposite sides, so as to interfit with the top of the cylinder 978. By the flanges 993 and the pin 992, the valve housings may be readily and quickly positioned, after which they may be screwed to the tops of cylinders by suitable screws 994.

The housing 991 has a bore 995 therethrough from end to end, in which the valve plug 996 is adapted to reciprocate. This plug is identical with the plug of the blank mold valve. Likewise the valve housing 991 is identical with the valve housings 271 and 851. The valve housing 991 is closed by a head or cap member 997, to which an inlet pipe 998 is connected. There are exhaust outlets 999 and 1000 leading therefrom.

The valve plug 996 has an axial bore 1001 extending inwardly from the inlet end thereof and connecting with two radial ports 1002 and 1003. Additionally, the plug has two peripheral exhaust grooves 1004 and 1005.

The valve housing 990 has ports that are adapted to register with the foregoing ports and to continue through the cylinder 978 to opposite ends thereof, as ports 1006 and 1007.

The valve plug may have suitable packing ring grooves, as shown.

The end of the valve plug is bifurcated to receive a cam roller 1011. These parts are identical with corresponding parts in the other valves. There is also a guide roller 1012 held by a screw 1013, the roller being operable within a slot 1014 in an arm on the housing. This roller thereby guides and limits the movement of the valve.

It will be seen that the introduction of air under pressure into the line 998 acts upon the right end of the

valve plug 996 (Fig. 47) to urge the valve to the leftward. This maintains the valve radially inwardly as far as it will go, and holds the cam roller 1011 against the cam track therefor when this cam track moves under the roller.

Blow mold operating cam

The cam track for the cam roller 1011 is supported on a collar 1018 and is shown in detail in Figs. 71 and 72. The collar 1018 that rests upon the main central column is formed of a split ring, as shown in Fig. 72, the two parts of which may be held together by screws that pass through ears on the two parts. At the top of the collar, there is a pivot ear 1021. Below this, there is a peripheral groove around the collar, indicated at 1022. Below the groove 1022, there is a projecting ledge 1023 that has a flanged cam element receiving portion 1024 provided with slots 1025. A cam element 1028 is secured to the portion 1024 by screws 1029 that pass through the slots 1025. By this means, the cam track element may be adjusted, and held in adjusted position, to vary the point at which the blow mold starts to open. The portion 1023 is likewise provided with an opening 1026. When the screws that secure the collar 1018 to the central column are tight, this collar is not rotatable on the shaft, and it may be secured against rotation by a setscrew 1027.

The peripheral groove 1022 is designed to receive an upper cam track ring, shown in Fig. 71, and generally indicated at 1030. It also is in the form of a split ring, the parts of which are held together by screws. In this case, the parts fit around the hub portion of the member 1018 by engagement within the groove 1022. When the screws are tightened for the member 1030, it still may rotate about the hub of the member 1018. The member 1030 has a ledge 1031 on its lower rim that receives a cam track element 1032, the same being secured thereto by three screws 1033. The ledge 1030 likewise has two arcuate slots 1035 and 1036 that are adapted to receive the two previously described operating shafts 909 and 928. The latter shaft also extends down through the hole 1026 in the ledge 1023 of the collar member 1018.

The member 1030 is oscillatable on the collar 1018 for adjustment purposes. The oscillating means includes a boss 1039 that stands upwardly from the upper surface of the periphery of the ledge 1030. To it, one end of a link 1040 is attached, the other end being pivotally connected with a crank 1041 that is pivotally mounted on the ear 1021 on the collar member 1018. It has a square opening to receive the squared portion 1042 of a shaft 1043. The lower end of this shaft is rounded off to fit into and bear in the opening through the ear 1021. The shaft 1042 extends upwardly to the top of the machine, where it has attached to its upper end a gear 1044 that meshes with a worm 1045 on a shaft 1046. This shaft is supported in a bracket 1047 and has a turn wheel 1048 on its outer end, and by means of which it may be adjusted. It may be seen that rotating the hand wheel 1048 will rock the crank 1041 and push or pull on the link 1040 to displace the cam track member 1030 about the groove in the collar member 1018. This will change the end point of the cam track elevation.

Blow mold cooling air nozzles

The wind columns 490 have previously been described as supporting the finish mold ring table 944 (Fig. 83). Above the flange of this table 944, there is an extension 1060 on each wind column. This extension has an enlargement 1061 at its lower end with a flange 1062 at the bottom. This flange engages in the hole that receives the top flange 942 on the main column 490. The parts are thereby accurately positioned.

The enlargement 1061 is hollow and has top openings 1064 and 1065 therein. The upper surfaces of the extension 1061 are finished flat, as shown in Fig. 83, and

have pins 1066 oppositely thereon. These pins receive openings in nozzle elements 1067 and 1068, these nozzle elements projecting in opposite directions and having passages 1069 therein that register with the openings 1064 or 1065 in the top of the extension 1061, and also open laterally and upwardly, as shown in Fig. 85. By this means, it will be seen that a nozzle member 1067 may cool the lower part of one blow mold, while the nozzle 1068 directs cooling air onto the lower part of an adjacent mold. It is shown in Fig. 83 that the cooling air from the column 490 passes upwardly into the base of the extension 1060. The nozzles may be quickly changed when the molds are changed.

Upwardly from the aforementioned extension 1061, the extension column 1060 has an enlargement 1072 that extends laterally to provide side ports 1073 and 1074. It also has finished upper surfaces on the opposite side of which the pins 1075 are located. Nozzles 1076 and 1077 are adapted to have holes that fit over pairs of the pins 1075 and extend downwardly to register with the ports 1073 and 1074 by nozzle passages 1078 and 1079, respectively. As shown on Sheet 17, these passages 1078 and 1079 project cooling air laterally and downwardly onto adjacent blow molds. The nozzles are also easily replaceable. Dampers may be provided to regulate the air delivery of these nozzles. Two such dampers are shown at 1080 and 1081. They slide in recesses milled into the contact faces of the nozzles.

Blow mold blow heads

The top of the extensions 1060 afford a support for a tie ring 1083, this tie ring being held by screws 1084 to the several composite columns formed by the wind columns 490 and their extensions 1060. A flange interfits these parts accurately. The tie ring 1083 is guided at its center part upon a flanged bearing member 1085 that rests upon the portion 170 of the center column and is keyed thereto by a key 1086. This key likewise engages the table 318 which bears upon the top of the hub support 1085. As is evident from the drawings, the tie disc 1083 is provided with spokes that join an inner hub section 1087 and an outer ring 1088. There is a screw 1084 connecting into a column 1060 at the outer end of each of the spokes.

The tie ring 1083 (Figs. 1, 2, 3, 77) is ten-sided, being straight between each successive screw 1084. Between each screw, there is a web portion 1090 that projects outwardly at its middle portion, as at 1091. Below this middle portion 1091, the bottom surface 1092 of the tie ring is finished. Also, the outer surface is finished at such point, as at 1093. The web 1091 receives a centering plug 1094 projecting therefrom. For each web 1090, there is a blow head cylinder adjustment bracket (Figs. 77, 82), generally indicated at 1095, that has a vertical surface 1096 adapted to register with the surface 1093 on the tie ring, and a horizontal ledge 1097 that is adapted to fit beneath the finished surface 1092 on the tie ring. These parts are adapted to be held together by screws 1098 extending upwardly from the bottom, and screws 1099 that extend inwardly from the sides of the vertical part. This arrangement provides for the quick and accurate location of the several blow head cylinder adjustment brackets.

Each of the adjustment brackets is provided with top and bottom walls 1100 and 1101 that are joined by a semi-cylindrical wall 1102. An adjustment screw 1103 is supported in the two walls 1100 and 1101, passing through both walls to provide a hand wheel 1104 at the top, and a securing means in the form of a nut 1105 at the bottom. It will be seen that the screw is reduced at the bottom where it passes through the wall 1101, and has a cross pin 1106 just above the wall 1101. The screw is freely rotatable, but prevented from axial movement.

The forward edges of the cylindrical wall 1102 are provided with two flanges 1107.

A blow head cylinder member 1110 is provided with a tongue 1111 that fits over the adjusting screw 1103. The cylinder casting likewise has lateral projections 1112 that fit against the flanges 1107 of the bracket 1095. The flanges 1112 engage the outer and side surfaces of the two flanges 1107 of the cylinder adjustment bracket. They are adapted to have jibs 1114 held thereon by screws, the jibs engaging the back surfaces of the two flanges 1107. By these means, the cylinders 1110 are caused to track accurately during vertical adjustment on the blow head cylinder adjustment brackets 1095.

Each cylinder has a head 1118 held thereto by screws, as shown. Also, each cylinder has a pair of air ports 1119 and 1120, one opening into the top of the cylinder and the other opening into the bottom thereof. At its lower part, the cylinder 1110 has a depending projection 1121, from which an air passage 1122 leads.

The cylinder 1110 receives a piston 1124, to which a piston rod 1125 is removably attached, as in the manner of previously described pistons. This piston rod is guided in the extension 1121, and is prevented from rotating by a screw 1126. Below the extension 1121, the piston rod 1125 has three projections 1127 that preferably extend out at 120 degrees to each other from the lower end of the piston rod 1125. Each has a vertical detent groove 1128 in its outer surface.

A blow head 1130 is fitted over the projections 1127. This head has a cavity 1131 to receive the projections 1127, the upper flange of the head over the cavity having three recesses 1132 complementary to the projections 1127. By this means, the blow head may be fitted over the projections 1127 and turned slightly, after which turning it is held to the piston. A leaf spring 1133 wraps around the outside of the head, yieldably urging a pin 1134 inwardly to engage in one of the vertical grooves 1128 in the projections 1127. It holds the head 1130 against rotation, and therefore holds it in place. The recess 1131 has a concave bottom surface 1135 which registers with a convex end surface on the piston rod, so that these parts are self-centering and self-sealing. The head 1130 has a lower recess 1138 adapted to receive the finish of the ware when the blow head is lowered onto a blow mold.

The piston rod 1125 has a bore 1144 extending upwardly from the bottom thereof and terminating in a radial port 1145. When the plunger is at its lowermost point, the radial port 1145 is adapted to register with an air passage 1146 that is connected with the air line 1122. The blow head element 1130 has passages 1147 therein that extend angularly therethrough.

When the piston 1124 is up, as shown in Fig. 77, the blow head 1130 is lifted off of the blow mold. When the piston is depressed, the blow head is brought down to engagement with the top of the blow mold and the interior recess 1138 is adapted to fit over the finish of the bottle with the lower edge of the cup-shaped member tightly engaging the top of the blow mold. The pressure causes a seal between the concave surface 1135 and the bottom of the plunger, so that the air pressure is maintained as the blowdown is produced. Also, the parts are self-centering to accommodate for minor variations in alignment of the parts.

Each piston 1124 is operated by a valve, generally indicated at 1150 (Figs. 3, 74). Each valve 1150 is mounted upon a supporting bracket 1151 that is held by screws 1152 to the lower surface of one of the spokes of the tie disc 1083. The valve itself is formed of a housing 1153 that is identical with the previous valve housings, such as the valve housing 991, although it is turned upside down and is screwed upon the bottom surface of the bracket 1151. This housing 1153 has a cylindrical bore 1155 therethrough that receives the valve plug 1156, this plug being identical with the plug 857 of the

pipe valve 850. The valve housing 1153 is flanged at 1157 to fit over the edges of the bracket 1151, and also is provided with a keyway to receive the key 1158. By these two means, accurate centering of the valve is obtained. It then is secured to the support by screws. It has a cylinder head 1160 that receives an air line 1161. The valve has a central bore 1162 with two radial ports 1163 and 1164. It also has two peripheral grooves 1165 and 1166. The housing has two exhaust ports 1167 and 1168 leading from the side thereof, these being spaced to register with the two peripheral grooves 1165 and 1166, respectively.

The housing likewise has two operating passages 1171 and 1172 that register with passages 1173 and 1174, respectively, in the bracket 1151, and from which the lines 1175 and 1176, respectively, lead to the bottom and top of the cylinder 1110.

The valve plug 1156 projects from the end of the housing, and, as in the previous valves, has a valve roller 1178 at the end thereof. This roller is adapted to be acted upon by a cam, generally indicated at 1180 and shown in greater detail in Fig. 73.

Blow head operating valve cam

25 The cam 1180 is mounted around the portion 169 on the center column. It consists of a central two-piece ring in the form of a main portion 1181 and a supplemental ring portion 1182 that are held together by screws. By this means, the cam may be engaged around the column. It is secured in position against rotation by a setscrew 1183.

The main member 1181 is in the form of an arcuate ledge. This ledge, on its right hand side in Fig. 73, has a depressed flange 1185 that is adapted to receive an arcuate cam element 1186. There are arcuate slots 1187 in the flange 1185, that are engaged by screws 1188 threaded into the cam element. When these screws are loosened, the cam track element 1186 may be moved arcuately, and thereby may alter the initial position at which the cam roller 1178 is displaced.

40 Clockwise around from the cam track element 1186, the ledge 1181 has an upstanding flange 1189 that provides another cam track element support means to receive an arcuate cam track element 1190. This element is retained on the ledge by a plurality of screws 1191 that pass through arcuate slots 1192, and are threaded into the ledge. This cam track element 1190 may move arcuately back and forth and may slide over the top of the track element 1186, which latter is flush with the bearing surface for the cam element 1190.

45 The arcuate adjustment of the cam element 1190 determines the point at which the roller 1178 will be released to move radially inwardly. This adjustment is accomplished by a link 1193 that is pivotally attached to the track element 1190 and to a crank arm 1194, which latter rests upon an ear on the hub of the member 1180. The crank arm receives a square shaft 1195 of a type previously described, which shaft is rounded to bear in a circular opening in the ear of a hub. The shaft 1195 projects upwardly through the top of the machine, and, above the table 318, has mounted thereon a gear 1196 that meshes with a worm 1197 on a shaft 1198, the shaft being supported in a bearing 1199 that is mounted upon the table 318. At its outer end, the shaft 1198 has an adjusting hand wheel 1200.

Feeder connection

50 Adjacent the nine-o'clock position, there is a feeder tube 1201, adapted to a guide a charge of glass into a blank mold. This feeder tube is preferably of the type shown in the copending application, Serial No. 688,471, filed August 5, 1946, by this inventor, which issued as Patent No. 2,598,955, June 3, 1952, being pivoted at its upper end adjacent the shears, and swinging at its lower end in synchronism with the travel of each blank mold as it passes the charging point.

Air distribution

The compressed air for the operation of this machine is introduced into the top of the center column 165 through a line 1205 at the top of the column. The column is hollow so that the air is conveyed to the bottom thereof where its egress is prevented by a plug 1206. However, adjacent the bottom, there is a radial port 1207 that leads into a distributor (Figs. 2, 3, 15).

This distributor includes a circular collar-like housing 1208 that is channel-shaped in cross section. It has a hole 1209 that is adapted to register with the radial port 1207 leading from the bottom of the opening 1205 in the column. The collar may be fixed by setscrews, such as the setscrew 1210, so as to be non-rotatable relative to the column.

This collar 1208 is adapted to receive a distributing ring 1212. This ring is adapted to be made in two sections that are held together by suitable screws 1213, appearing in dotted lines in Fig. 15, it being understood that corresponding screws are disposed diametrically opposite those as illustrated. The two halves are fitted into the channel of the collar housing 1208. The two halves are provided with complementary semicircular passages that provide an annular passage 1214, into which the port 1209 opens. It will be seen that the annular passage or chamber 1214 is thus always provided with compressed air from the column.

Each section of the distributor ring is provided with a groove, into which a semi-circular packing ring 1216 may be inserted. These rings are fitted over pins 1217, by means of which they are positioned and held against displacement. They are also acted upon by a plurality of coil springs 1218 that urge them outwardly against the surfaces of the collar 1208. The ring sections are also adapted to have a close fit at their side edges with the edges of the channels into which they fit. The distributor ring may have suitable oil grooves, as shown.

Each of the two distributor ring sections is provided with a laterally projecting ear 1220 that has a hole to receive a driving pin 1221. The two driving pins are held by screws to the top of the vacuum distributing member 669, as shown for example in Fig. 2. By this means, the rotation of the member 669 will cause the rotation of the distributing ring 1212.

The distributing ring is adapted to have five discharge openings 1223 projecting therefrom.

The machine is provided with five air pressure manifolds 1225. Each manifold takes care of two adjacent forming groups. As shown in Fig. 65, these manifolds are bracketed to the blow mold ring 944, so that they are supported thereby. A distribution pipe 1226 connects each of the manifolds 1225 with one of the holes 1223 in the distributor.

The manifolds are shown schematically in Fig. 92, along with the other parts of the air distribution mechanism. The manifolds 1225 may take the form of vertically disposed pipes, from which the several connections may lead to the operating elements of the mechanism. Fig. 92 shows only a single set of connections to each manifold, leading to a single set of molds. With the exception to be noticed, all of the outlet lines are duplicated to care for two molding groups.

The operating valve of the blank mold cylinder has already been described as having an air inlet line 277. The line is connected into the manifold 1225, as shown in Fig. 92 (compare Fig. 47). The plunger cylinder for the blank mold is shown as being operated under control of the valve 348 which receives its air from a line 351, connected into the manifold 1225.

The operating valve for the baffle arm cylinder receives compressed air through a line 553, connected into the manifold 1225.

The operating valve 850 of the transfer mechanism re-

ceives compressed air from the inlet line 855, connected into the manifold 1225.

The operating valve for the blow mold cylinder receives compressed air through the intake line 998, which is connected into the manifold 1225.

The operating valve of the blow head cylinder receives compressed air through the intake line 1161, which is connected into the manifold 1225.

It is desirable that the counterblow in the two molds be produced by a low pressure air, so that it will be softer and more gentle in its operation. To this end, there is a supplemental manifold ring 1230 that is mounted on the blow head supporting disc 1083. This ring is provided with two concentric annular manifolds 1231 and 1232. As shown in Fig. 1, the disc 1083 also supports a pair of pressure reducing valves 1235 and 1236. The reducing valve 1235 connects into the inner annular manifold 1232, whereas the pressure reducing valve 1236 connects into the outer manifold 1231. Two of the vertical manifolds 1225 have lines 1237 and 1238, respectively, that lead into the two pressure reducing valves 1235 and 1236. The annular manifold 1232 is connected into the line 445 that leads to the blank mold counterblow mechanism; the manifold 1231 is connected to the line 1122 that leads to the blow mold head for the counterblow therein.

The process

The process which this machine is designed to practice comprises the introduction of a charge of glass into a blank mold, the formation of a particular blank therein, the transfer of the blank to a finish mold, and the completion of the ware in the finish mold. All of these operations take place during the continuous rotation of the machine.

For the particular type of ware illustrated, which happens to be light-weight, short, eight-ounce bottles, the rotation of the machine is set at six revolutions per minute. The machine is designed to employ one and one-half revolutions for the complete processing of any bottle. Therefore, it will be seen that it requires fifteen seconds for the fabrication of any bottle from the introduction of the charge to the withdrawal of the completed ware. This mold rate is seen to be adequately slow to enable ware to be properly made. It is, of course, varied by changing the speed of the machine. In general, the machine is slowed down for larger ware and speeded up for smaller ware. The two circles in Fig. 93 have been graduated to indicate time in seconds, it being understood that these times are typical for the particular size and shape of ware being produced. It will be evident that the division of the time of a cycle is different in this process over prior processes.

After a charge is introduced into a blank mold, the finish is formed by the fact that the plunger is brought up and vacuum is on at the time the charge is received. The operation is performed as rapidly as possible. It will be understood that the elevation of the plunger is accurately timed with the descent of the gob into the bottom of the mold, so that neither overpress or underpress results. The plunger is normally almost seated in the neck rings when the gob strikes it, and vacuum is on the plunger, as will appear, because the port 460 has begun its passage over the top of the cone 336, and the valve 478 is open. The vacuum lasts only a part of a second, after which the plunger is withdrawn, and, at about one second's interval, the baffle head is introduced over the blank mold, and shortly thereafter the counterblow begins.

The formation of the finish requires a very short period, and the counterblow begins almost instantly, which reduces sharply the likelihood of there being a ring in the ware at the top level of the charge after the pulldown.

This speed of forming the finish aids in reduction of the

ratio of finish forming time to total blank forming time, and increases the available interval for the counterblow and dwell of the parison in the blank mold. It may be seen that in the illustrated operation of Fig. 93 the counterblow begins somewhat less than one and one-half seconds after the charge is introduced into the mold, and less than one second after the pulldown is completed.

The counterblow is completed in something over four seconds, after which time the baffle is withdrawn and the transfer head starts down. However, the blow mold does not begin to open until after seven seconds. The long parison forming period means that the blank is in contact with the walls of the blank mold for a period of approximately five seconds in the illustration given, out of a total of fifteen seconds for the entire cycle.

The long period of dwell of the parison in the blank mold has numerous advantages. One of the functions of glass-forming molds is to dissipate heat from a charge of glass so that the finished ware taken from the forming machine may be handled. Stated otherwise, the glass must be sufficiently hot when delivered to the mold to be formed thereby, and the customary limiting factor requiring highly heated glass is the formation of the finish. The charge must be initially hot enough to make the finish. The final ware must be cool enough to be handled, which usually means cool enough to be taken out of the finish mold mechanically, delivered to a lehr loader, and annealed without losing shape. The difference in heat content must be dissipated during the molding operation, which largely involves dissipation into the molds themselves. The molds are designed to control the rate of dissipation.

In the present process, a greater percentage of heat is dissipated into the blank molds than in former processes. The transfer operation occurs later, with respect to the heat dissipation, than heretofore. This has the dual effect of making the transfer more satisfactory, and producing improved ware.

The transfer is more satisfactory because the parison is stiffer and relatively self-sustaining, with less likelihood of deformation, as by inertia effects, in its displacement from the blank mold to the finish or blow mold. As will appear, the transfer of a stiff parison is rendered possible by a novel method of handling the parison for this step.

The making of a stiff parison improves the quality of the ware for several reasons. In the first place, a protracted dwell in the blank mold tends to even out temperature irregularities such as hot spots, present in the glass when it is delivered to the mold. This makes production of lighter weight ware feasible. Further, the glass beyond the finish and beyond the neck just below the finish is held in contact with the mold for a long enough period to give more even skin thickness around the parison. Heretofore, the finish and adjacent parts were in contact with the mold a much larger percentage of the total time of formation of the parison. In other words, decreasing the ratio of finish making time to total parison forming time improves the evenness of surface distribution and skin on the parison. The present process improves the ratio by minimizing the finish forming time between charging and counterblow, and protracting the counterblow and dwell interval.

Hence, when the parison is deposited into the blow mold and the final blowdown begins, the glass near the bottom, where, in hollow parisons, the expansion of the parison starts, is nearer the temperature adjacent the finish. This, together with other features of the process to be described, reduces the tendency toward thick shoulders and uneven walls, particularly walls that are thin toward the bottom. It reduces the stress at points where light walls would be produced as a result of abrupt changes in temperature.

The foregoing provides a parison stiff enough to main-

tain its shape during transfer and disposition in the blow mold, as contrasted with conventional practice wherein the parison is necessarily kept highly heated until the blow mold operation is finished. Comparing the times for the formation of the blank with the time for formation of the final ware from the blank, it will be seen that the formation of the blank consumes about one-half of the total cycle, whereas the formation of the completed bottle from the blank requires the remaining half, minus the time required for the transfer.

Another feature of the present process is the formation of a blank or parison that has substantially the same length as the finished ware. This provides a blank that may be supported by its bottom in the finish mold, so that the stretching-down or running of the parison in the finish mold can be eliminated, with attendant reduction of inequalities of glass distribution, of settle waves, and other defects. The parison is introduced into the blow mold by being held at its bottom; and the blow mold is closed around it. The stiff parison is self-supporting, so that it holds its shape and can be engaged by the blow mold in the manner shown.

A further feature of the present process is the formation, in the blank, not only of the finish in its completed form, but also of a portion of the bottom of the blank into its completed form. At least there is a portion opposite the finish that is completed sufficiently for two purposes. The first purpose is to enable the blank to be vacuum-held by this portion for the transfer, and the second is to enable the blank to be supported to at least a partial extent at its bottom when it is subsequently disposed in the finish mold. Further explanation of this latter will follow hereafter.

The process employed in the blank molds involves a very rapid pulldown of the charge of glass, followed very promptly by a counterblow; it includes the relatively slow counterblow and the long dwell of the blank within the blank mold, and the consequent formation of a stiff parison. It involves the formation of finished portions of the final ware in the blank that are oppositely disposed, so that the blank may be supported both at its top and at its bottom in the blow mold. As a consequence to the foregoing, the process involves the material reduction of the temperature differentials between the finished neck or finished portion of the ware and the remaining parts.

After the lapse of seven and one-half seconds in the present illustration, the transfer begins. The process involves transferring the parison by the vacuum head which engages the completed portion on the bottom of the parison opposite its finish. The transfer mechanism thereby engages a relatively stiff blank toward its heavier end, so that, in the inversion of the blank, the centrifugal forces are reduced, as are the inertial forces that tend to distort the blank. The formation of a stiff blank also reduces distortions that would normally occur during the transfer operation.

The engagement of the blank at the bottom portion, as aforesaid, and its transfer without the presence of the conventional neck ring operation, or the clamping transfer operation, leads to much smoother handling of the blank. The engagement of the vacuum head of the transfer with the parison is clearly a gentle operation. In other words, this transfer operation of the present process eliminates the rough handling characterizing former processes, and thereby eliminates small fractures in the finish, known as checks, that frequently occur in the former operations.

Furthermore, the possibility of the formation of such checks in former processes has forced the use of hotter and less stiff blanks in such processes. It may be seen that formation of the relatively stiff blank in the blank mold is functionally tied to the present transfer operation.

Another feature of the present process is that the parison is contacted on its large and relatively hot base, which is in no wise as subject to checks as is the finish

which is held in the conventional transfer operation. Furthermore, the vacuum head of the transfer mechanism becomes the bottom of the blow mold, the end portion 780 thereof being enclosed within complementary grooves 1240 at the bottom of the mold, as illustrated in Fig. 78. This, of course, insures that the pattern or parison is properly disposed with respect to the bottom of the finish mold from the very beginning of the finish mold operation. It eliminates heel taps and leads to the more even distribution of the glass in the bottom of the ware. As already noted, the parison is stiff enough to remain upright and of constant length until the blow mold closes on it. The blow mold engages the top of the parison below the finish, and the parison must be stiff enough not to settle prior to such engagement.

After the transfer has taken place, the blow mold closes rapidly on the parison. As shown in the top circle of Fig. 93, the transfer may be completed at about eight and one-half seconds after the beginning of the cycle, and almost immediately thereafter the blow mold is closed on the parison.

As already noted, the parison is supported in the blow mold just beneath the finish, and also at the bottom, which bottom is resting upon the vacuum head that forms the bottom plate for the blow mold. The run or stretch-down of the parison is eliminated.

After the blow mold is closed, a reheating period may be provided. This is shown as an interval of approximately four seconds. During this time, the enamel or skin on the surface of the blank is reheated by the contained heat of the inner glass of the parison. By virtue of the gravity situation, resulting from the support of the blank at its bottom, there is a much reduced tendency of the glass to settle toward the bottom during this operation and a more even reheating is obtained. This reheating period can be usually longer than conventionally, because of the fact that the parison is cooler and stiffer than conventional parisons. Obviously, the reheating is more even with this arrangement. It may be commented that the length of the reheating period may be widely varied. In heavier ware particularly, the blowdown may be started earlier. The blowdown may be begun as early as the dotted line position in Fig. 93.

Another feature of this process is that, in this arrangement, there is only a single counterblow. This eliminates the requirement of maintaining a substantial amount of solid glass at the bottom of the parison sufficient to reheat the bottom to produce the required weight of glass in the finished ware in that area. Such massing of glass in the parison at the bottom produces unsteady distribution and excessive reheating of the enamel in this portion, which latter potentially lays ground for a blow-through of the bottom of the parison.

Thus the present process provides a blank of desirable characteristics and size, transfers it to the blow mold with maximum facility and minimum damage, reheats it as needed in the blow mold in a manner that will obtain most desirable distribution, and finally blows it down at a proper rate of speed, with the over-all result of a highly desirable end product.

The foregoing treatment of individual charges of glass is multiplied by the present machine, which has a plurality of molds successively operating. As already stated, the machine operated as illustrated produces sixty bottles a minute from a single charging device. This rate of production is substantially higher than comparable machines, of which a typical one produces about thirty-five to forty bottles per minute. Furthermore, the present process produces better bottles, having much more satisfactory distribution of glass, with a much smaller percentage of rejects.

This process lends itself to one-man supervision and operation. The glass is charged at one point, and discharged at what may be a diametrically opposite point, in a machine embodiment such as that shown. Both

points are critical in glass manufacture, and both may be easily observed. The transfer zone is critical. By having a lengthened parison forming period, the transfer zone may be located between the two previous points and be readily accessible. The use of this method of transferring, which eliminates many parts, and certain operations requiring split-second timing, simplifies the process to such a degree that it may be easily cared for by one man.

It is further evident that the speed of this machine may be greater or slower for bottles of different sizes and weights. It is, of course, evident that it is capable of making many sizes of containers, such as those that are very small up to those of one-gallon capacity. The process is likewise not limited to small-mouth container ware, although certain features of the process are peculiarly applicable thereto.

The foregoing represents generally the new process of this application. Certain process phases are better described in connection with machinery for performing them, and will appear hereafter.

Operation of the machine

The datum point for the start of the machine is at the nine-o'clock point on the lower circle of Fig. 93. This is the point at which a charge or gob of glass is introduced into each blank mold.

At the start of any operation of this machine, power will be introduced, by any suitable control device, through the chain drive 234, which causes rotation of the shaft 229. This is followed by rotation of the gears 228 and 227, and the vertical countershaft 226, so that the small gear 225 rotates the large gear 215 that is secured to the bottom of the rotating table 190. The table 190 rotates continuously about the base on the roller bearings 220.

It may be seen from the full description of the parts that the rotating mechanism includes the table 190, the wind columns 490 with their extensions 1060, joined by the table ring 944, and the upper disc 1083, which last named disc is journaled to the column. Upon these parts, as a movable framework, the blank mold assemblies are mounted (upon the table 190), the transfer mechanisms are mounted (between adjacent cooling air columns 490), the blow mold assemblies are mounted (on the table ring 944), and the blow heads are mounted (on the disc 1083). The cam tracks remain stationary on the base and the column.

Also, at the start, suitable air pressure will be introduced through the line 1205 into the top of the column 165. This compressed air is transmitted to the bottom of the column and out through the air distributing mechanism. It passes through the port 1207 in the lower part of the column, and thence through the port 1209 and into the distribution chamber 1214 (Fig. 15), whence it passes out into the several pipes 1226 to the manifold air columns 1225 (Fig. 92). The distributing ring 1212 is caused by the pins 1221 to rotate with the table, and its arrangement provides a seal between the rotating and fixed parts. The manifold columns rotate with the table 190. From these columns 1225, compressed air is distributed in constant supply to the control valves of the several mechanisms, as shown.

In addition, at the start, two of the manifolds 1225 deliver air through the lines 1237 and 1238 that lead through the pressure reducing valves 1235 and 1236 to the annular manifolds 1231 and 1232, formed in the ring 1230 (Figs. 1, 92). These manifolds thereby receive air at reduced pressures. Each may be individually controlled by its pressure regulator. For example, in certain operations, the pressure in the outer manifold 1231 may be 24 p. s. i., and that in the inner manifold 1232 35 p. s. i. The manifold 1232 delivers air through the line 445 to the valve cylinder 435 for the counterblow of the blank mold. The other manifold 1231 delivers air through the line 1122 to the blow head piston rod, the lower part of which acts as a valve.

In addition to the compressed air situation just set forth, vacuum is also made available at the start. The line 134 leading through the base is connected to a source of suction. This line leads into the vacuum chamber 151 and constantly draws a vacuum in the chamber 669, through the slots 679 and the ports 680 (Figs. 2, 16). The chamber 669 is constantly connected by the two pipes 665 and 666 through the fittings 667 and 668 with the annular vacuum chamber 196 of the rotating table 190, which thereby constantly has vacuum, for use in the pull-down in the blank molds, and in the transfer mechanism. The chamber 190 provides a vacuum reservoir in proximity to the vacuum operated parts; and makes possible a solid vacuum connection to the heads, as well as to the valve controlling vacuum for the transfer heads.

In addition to the compressed air and vacuum, as aforesaid, there is a cooling air supply that is constantly on. This cooling air supply is delivered through the lower cylindrical opening 132 in the base from the cooling air duct 129. It then is discharged upwardly into the compartment 150 (Fig. 2) at the bottom of the column. This chamber 150 is in constant communication through its ports 152 and the ports 207 into the bottom of the rotating table 190, so that the various sectorial chambers 200 in the rotating table are charged with cooling air. This air is delivered upwardly through the ports 208 of the sectorial compartments 200 of the table 190 to the several columns 490, their extensions and nozzles, to cool the molds, as will appear.

The foregoing gives the status of the elements at the nine-o'clock position which is chosen as the start. This position is shown in Fig. 93. There is a swinging feeder tube 1201 (Fig. 2) that receives a charge of glass that may be in the form of a gob, preferably from a synchronized feeder (not shown). The feeder tube is caused to be rocked with the forming machine, so that the charge of glass may be introduced into the blank mold at the time the table 190 is in a state of continuous rotation. This charge of glass falls by gravity to the bottom of the blank mold 253a, which is closed at this point. Likewise, at this point, the plunger 401 is approaching its upper position that is shown in Fig. 33. This position of the plunger is brought about by the fact that the plunger cam roller 355 has engaged the track 603, to raise the valve plug 354. The air line 351 to this valve constantly receives air from a manifold 1225 at a flow rate determined by the needle valve 368. The air flows from the plug 354 through the passages 360, 361 and 363 to the lower side of the piston 343. The piston rises against the spring 344 at a controlled speed, and thereby relatively slowly introduces its upper parts into the complementary parts of the bottom of the mold. The reduced speed prevents damage in this engagement. It also controls the engagement between the gob of glass and the plug 402.

At the charging point, the vacuum chamber 335 of the particular mold is connected to the annular vacuum chamber 196 of the table 190 because the valve 478 is open, its cam roller 481 having ridden onto its cam track 576. The vacuum in the chamber 335 is transmitted upwardly through the ports 392 and the spacer sleeve to the ports 396 in the head 395. From these ports, the vacuum is pulled at the top and the bottom of the finish. It is pulled at the upper part of the neck rings by the connections comprising the vertical passages 416, which open across the sloping surfaces 420 and the clearance 422 at the top of the neck rings. It is also pulled through the grooves 400 to the bottom of the finish, as the gob is positioned in Fig. 33.

At the same time, the plunger plug 402 is approaching its upper position. The ports 460 are shaped and sized to project beyond the conical sleeve 336 as the plunger approaches the upper end of its stroke. Consequently, at the time the charge is received in the mold, there is a vacuum drawn through the interior of the

plunger and through the passages 395 to the bottom of the finish. There is sufficient clearance around the plunger to permit this vacuum to be drawn between it and the adjacent parts of the head 395 that receive the plunger.

5 The plunger rapidly seats in the head to form the finish completely with the insert therein caused by the plug 402. The coordination of the introduction of the gob into the mold and the travel of the plunger upwardly is such as to prevent either over pressing or under pressing. 10 The speed of travel of the plunger may be regulated during the operation of the machine by adjusting the needle valve 368, coupled with the proper initial adjustment of the plunger cam track 603, so that its initial end piece 605 is engaged at the proper time by the cam 15 roller 355, which adjustment likewise may be made while the machine is operating.

The drawing of vacuum at the top of the neck rings prevents a pull away of the glass at this point.

The foregoing charging and finish forming operation, 20 as indicated in Fig. 93, continues for something under 30° of rotation of the table, which requires somewhat more than one second in the illustrated machine. This is sufficiently long to permit the glass to be pulled down and to complete the finish of the ware to the point shown 25 in Fig. 33. Thereupon, the cam roller 481 of the vacuum valve 478 falls from the cam track 576 and the valve closes. This cuts off the vacuum from the bottom of the mold. At about the same time, the plunger valve cam roller 355 is dropped by the plunger cam track 603, whereupon compressed air constantly available in the line 351, acting upon the top of the plug 354 of this valve, causes it to descend rapidly. Its descent removes the port 361 from communication with the port 363 (Fig. 26), so that compressed air is cut off from below 30 the piston 343. Likewise, the area below the piston is then put into communication with exhaust through the peripheral groove 362 and the exhaust passage 353 leading from the valve housing 348. The piston 343 is then caused to descend by the spring 344.

40 The descent of the piston 343 withdraws the plunger and the plug 402 to the position shown in Fig. 41. This operation withdraws the vacuum ports 460, leading from the internal passage 426 of the piston rod, out of registry with the vacuum chamber 335 in the bracket 330. The descent likewise introduces the air inlet port 428 of this same axial passage 426 to the air inlet passage 431 connected with the air line 432 (Figs. 26, 41). This air line 432 leads from below the poppet valve 435 (Fig. 27). The valve head 440 is at this point closed, so that the counterblow air is not yet introduced to the bottom of the mold.

45 As the table continues to rotate, and at about the same time that the vacuum is relieved and the plunger descends, the baffle cylinder valve cam roller 566 (Fig. 29) drops from the track 615. This admits compressed air through the valve 560 to the line 556 leading to the upper side of the piston 520 (Fig. 31), and causes this piston to descend. At the same time, the line 555 from beneath the piston is connected by the valve 550 through the 50 peripheral groove 565 with the exhaust port 557.

55 When the piston 520 descends, it is forced to twist, owing to the engagement of the cam roller 544 in the slot 545 in the track member 512. This causes the arm 523 (Fig. 42) carrying the baffle head 540 to descend and twist over onto the top of the blank mold, and finally to move vertically to interfit into the recess provided therein. (Compare stations *a* and *b* in Fig. 18.)

60 After the baffle head has been duly seated by the foregoing action, the counterblow valve roller 452 will ride up onto the counterblow track 635 (Fig. 6), this operation beginning after about one and one-half seconds in the illustration. As shown in Figs. 23 and 27, this will cause the counterblow valve 440 to open, whereupon the relatively low pressure air from the line 445 is admitted 65 to the line 432. As shown in Figs. 20 and 26, the line 70

432 communicates with the passage 428 leading to the interior axial passage 426 in the plunger. This counterblow air then passes upwardly through the passage 425 in the spacing extension 381 and out through the angular ports 403 (Fig. 41) in the cap of the plunger. It is then discharged into the recess formed by the plug 402 in the bottom of the charge of glass, and causes the glass to expand upwardly, filling the blank or parison mold, and forming a portion of the bottom against the baffle plate 540.

The counterblow air is continued from a point between the ten- and 11-o'clock positions of Fig. 93 around to about the two-thirty-o'clock position, about four and three-quarter seconds after the charge. It is very desirable that this counterblow be given sufficient time and operated with sufficiently low pressure to obtain desirable forming of the parison without pulling the finish away. Excessively rapid counterblow gives unequal distribution of the glass in the parison. Also, the continued application of pressure causes the blank to fill out all parts of the blank mold and to rest firmly against the seat provided in the bottom of the baffle plate 540, and a long parison dwell gives a stiff parison, as previously described.

Thus, at approximately the two-thirty-o'clock position, the cam track 635 (Fig. 6) terminates, and the counterblow cam roller 452 is released, so that the valve 440 (Figs. 23, 27) can close under the influence of its spring 441. This closing action is augmented by the air pressure differential which provides a higher pressure on the top of the valve. It will be observed that, as this valve 440 is a poppet valve, it is moved by a relatively small amount of motion, which is provided for by the rocker arm 448. When the valve closes, any air behind it may escape out the groove in its stem, which opens only when the valve is down.

With the counterblow completed, the table in its continued rotation again brings the baffle cylinder cam roller 566 to the baffle cam track 615 (see Figs. 6, 93). This again elevates the valve 560 and introduces the pressure through the axial passage 561 and the port 563 to the line 555 leading to the cylinder 514 below the piston 520; and simultaneously introduces the line 556 above the piston 520 to exhaust by way of the peripheral groove 564 and the exhaust port 558. Thereupon, the compressed air elevates the piston 520 and swings the baffle head off of the blank mold.

Shortly thereafter, as shown in Fig. 93, the transfer piston operating cam roller 869 is brought against the combined cam track element 916 (Figs. 57, 58). This engagement will cause the transfer valve 857 to be displaced outwardly, connecting the port 859 from the axial passage 858 with the passages 863 and 865 leading to the inner end of the piston 694. Likewise, it will cause the other end of the cylinder to register through the passages 866 and 864 with the peripheral groove 862 that now registers with the exhaust port 867. As a result of this shift of the valve, compressed air, constantly available in the line 855, will be admitted to the inner end of the piston 694 which will thereupon move radially outwardly.

Outward movement of the piston 694 will shift the piston rod 695 outwardly toward the position of Figs. 48 and 49. The movement of the piston rod 695 will move the crosshead 702, which is tracked between the projecting walls 703 of the transfer support 685 and the jibs 709. The outward movement of the crosshead 702 will carry the threaded sleeves 711 away from the springs 719, which are thereby relieved of compression.

The outward movement of the piston rod 695 likewise displaces the turnbuckle 727, which constitutes a pivoted link between the piston rod and the bell crank arm 731. As the bell crank moves, it rocks about its sleeve portion 732 that pivots on the pin 733 supported in the two bearing ears 734 that are part of the transfer head base 685. This rocking movement of the bell crank 731 carries its outer end 739 in an arcuate movement about

the pin 733, so that the outer end 739 moves from the dotted line position of Fig. 49 to the full line position.

The vacuum head 775 is rotatably mounted upon the end 739 of the bell crank member 731. It is also connected by the slotted link arm 791 with the upstanding bracket 787 that is secured to the transfer support 685. This link, the spindle 747, and the sleeve 753 are all rigidly connected; and the sleeve is connected by engagement of the lug 755 thereof between the screws 758 with the transfer head assembly. The link 791, on the other hand, has slotted engagement with the fixed roller 789 (Fig. 78) on the upper end of the arm 787. Thus, the vacuum head not only moves in an arcuate direction, about the pin 733 of the bell crank member 731, but also rocks about the bearing 741. In the illustration, 90° of rotation of the vacuum head are provided by rocking the bell crank member 90°, and an additional 90° are provided by the link 791, so that the vacuum head rocks 180° with a relatively small radial displacement.

In seating in either of its molds, the vacuum head automatically centers itself to compensate for minor variations in the proper shaping and dispositions of the parts. As shown in Figs. 55 and 78, the sleeve 742 has a recess receiving a flange 783 on the transfer head proper. The recess is slightly larger in diameter than the outer dimension of the flange. The pins 765 are arranged to permit slight lateral movement of the transfer head on the sleeve without losing the vacuum seal. This is provided by the slightly larger size of the openings, into which the several parts of the pins 765 fit, than the corresponding sizes of the pin portions. Thus, the reduced part of the pin shaft beneath the wedge head 769 is slightly smaller than the lateral dimensions of the openings in the vacuum head flange 771 through which these parts pass. However, the wedging heads exert a constant sealing force between the members, so that their finished and flat surfaces are held in engagement despite the slight lateral movements. As a result of the foregoing, the transfer head seats firmly in the top of the blank mold, which is, of course, closed.

After the transfer head has started down, to replace the baffle head on the blank mold, vacuum is drawn through the vacuum head. This is brought about by engagement of the cam roller 813 of the transfer vacuum valve 809 (Fig. 21, Sheet 6) with the track 818 (Fig. 6), and consequent opening of the valve 809, to connect the line 801 to the vacuum head. The vacuum leads from the multiple ports 782 of the head through the head passage 781, the passage 841 of the swinging head 742, thence through the passages 840 to the interior of the bell crank head 739, down the passage 837 in the bell crank arm 738, to the recess 837 in the base part thereof, and through the holes 836 to the bore 835 that is connected to the line 801. This vacuum is available as the vacuum head seats on the blank mold. The vacuum head is accurately shaped to interfit with the finished bottom of the blank that was formed by the baffle plate, so that the blank is promptly held securely to the vacuum head.

Shortly after the transfer head is seated onto the blank mold, the latter begins to open. This operation is effected by engagement of the cam roller 291 of the blow mold control valve 270, with the track 307 (Figs. 46, 47), to shift the valve plug 275 outward. When the plug 275 is outward, compressor air is valved through the axial passage 282, and the port 284 to the passage 288, to the outer end of the piston 260, the inner end being connected to exhaust by the passage 287, the groove 285, and the exhaust port 279. The piston 260 moves inward, drawing the yoke 258 inward, and opening the mold sections by the links 259. When the mold is open, the blank is supported wholly by the vacuum head.

At the six-o'clock position, seven and one-half seconds after the start, transfer begins. The transfer valve cam roller 869 leaves the cam element 886, and air from the

line 855 forces the valve plug 857 inwardly. This, as shown in Fig. 47, ports air through the axial passage 858, the port 859, and the passages 863 and 865, to the inner end of the piston 694, the other end being exhausted through the passages 866, 864, the groove 862 and the exhaust port 867. The piston thereupon moves inwardly, causing the vacuum head 775 holding the blank to swing 180° (reversing its former movement) to introduce the blank into the blow or finish mold.

At the latter part of the transfer operation, the cross-head 702 brings the sleeves 711 against the decelerating cushion springs 719, slowing the end of the operation and causing the blank to enter the finish mold without serious distortion.

This transfer point is indicated in Fig. 93 by the line connecting the bottom of the lower circle with the lower part of the upper circle. From this point, the blank mold part of the machine prepares itself to receive another charge of glass, while the blow mold proceeds to treat the parison that is transferred.

The blank mold, at the point of transfer, is open. It continues in the open condition for about 40° until the cam roller 452 of the counterblow valve 440 strikes the short track 644 (Fig. 6), and the counterblow valve is again opened. During this travel from the point of transfer until the roller 452 engages the track 644, an atomized spray of mold oil consisting of a lubricant and certain carbon colloids is sprayed into the mold by means (not shown) auxiliary to the disclosed glass machine. Inasmuch as an excess of lubricant remaining in the blank mold at the time of charging the same will produce deleterious gas pressures therewithin, it is necessary to purge any such excess before the charging point is reached. It will be remembered that the plunger is still down, having been released to the lower position when the plunger valve roller 355 was released by the track 603. Consequently, the counterblow air is admitted through the registry of the port 428 of the piston rod 345, and can be directed outwardly by the sloping ports 403 and the upper part of the head 398 to the interior of the then open blank mold sections 254 and 255, to purge the mold interior of excess lubricant. While this blowing takes place, the blank mold valve roller 291, controlling the valve 270, begins to be released by the segment 305 of its cam track, so that the compressed air acting on the outward end of the valve head 275 forces the same inwardly and shifts it so that the radial port 283 comes into registry with the passage 287 in the cylinder, and compressed air is put to the inner end of the piston 260, forcing it outwardly. Likewise, the other end of the cylinder is admitted to exhaust by the registry of the passage 288 with the peripheral groove 281 and the connection of the latter with the exhaust port 280.

The blank mold sections, as shown in Fig. 18, are forced closed by the action of the yoke through the link 259. Shortly before, or at about the time of the closure, the counterblow cam roller 452 drops from the short track 644, and the counterblow air is cut off from the blank mold. It then continues to rotate in closed position, until it returns to the starting position to receive another gob and to start a subsequent forming operation.

As the blank mold sections close, they engage and interfit with the head 399 on the cap 395. The upper and under surfaces of the flange on this head slope, so that engagement can be made despite slight misalignment of the parts. As the closing continues, the recesses in the blank mold parts engage the sloping under surfaces of the flange and lift the entire cap 395 slightly, until the two sections are tightly closed. The deep skirt on the cap 395 has a long sliding fit with the spacer 383 to permit this movement without leaking. The flange not only assures a tight fit of the parts, but also provides accurate relative positioning of the two mold sections, which become located by it.

The neck rings are preferably slightly loose between

the screws 410, so that their interfaces will be brought together evenly and tightly.

In the reopening of the mold, previously referred to, the mold sections withdraw from the flange, whereupon the cap 395 again descends onto the spacer 383. This provides clearance between the bottom of the mold sections and the mold head, so that a smooth break of the mold results. This reduces likelihood of pulling the parison with one mold section, and breaking the vacuum between the transfer head and the parison.

It will be noted that, with separate spacers 383, the caps 395 may be closely uniform in weight, so that the lifting load on the mold sections does not greatly vary for different ware.

At the time the transfer is completed and the initially formed parison is disposed in the upper circle of the blow molds, the particular mold into which the transfer is made is open, as appears from Fig. 64. This mold that constitutes the starting mold for the blow mold operation is at about the seven-o'clock position. Prior to the transfer operation, the roller 1011 of the blow mold control valve 990 is brought into engagement with the cam track 1028. Very shortly after the transfer is completed, this cam roller 1011 begins to move inwardly by release from the end of the track member 1032, and air pressure against the outer end of the valve plug 996. In moving in, it shifts the valve plug 996 from the position shown in Fig. 47 to bring the radial passage 1002 into registry with the passage 1006 of the cylinder, and thereby to admit compressed air to the inner end of the piston 977. At the same time, the other end of the piston is connected to exhaust by the registry of the passage 1007 with the peripheral groove 1005 that is connected to the exhaust port 1000. The piston thereby moves outwardly, and, in so doing, the piston rod moves its yoke 973 and the links 971, so as to close the two mold sections 964 and 965. These mold sections close on the transfer head member 780, as shown in Fig. 78. This member, as already noted, is self-sealed into the blow mold sections and forms the bottom plate thereof. It aligns the blow mold sections in a manner similar to the action of the flange on the cap 396 upon the blank molds. When this operation is completed, the cam roller 813 of the vacuum valve for the transfer is released from the cam track 818, so that the vacuum is withdrawn from the transfer head. The transfer head thereafter continues to travel with the blow mold, and to form a bottom part thereof. By the accurate positioning of the transfer head into the blow mold, proper centering of the parison in the blow mold is assured, and heel caps and like blemishes are substantially eliminated.

It will be seen that the transfer takes place by a vacuum grip of the finish part of the bottom of the ware, so that the ware is held to the vacuum head. The transfer swings the ware while it is so held, but the attachment is at the bottom which is at the heaviest part of the parison. Thus, centrifugal force is minimized. Furthermore, the transfer takes place by the reversal of the valve 850 and the admission of air to the inner end of the piston 694, causing the crosshead 702 to be drawn inwardly. Toward the end of this inward stroke of the crosshead, the two threaded sleeves 711 are caused to engage the outer free ends of the two springs 719. The end of the transfer operation is cushioned by the compression of these two springs 719. As a result, the transfer swinging takes place at a fixed speed for its initial part, but the end of the transfer takes place with constant deceleration by the increase in the force exerted by the spring 719, with the result that a slow ending of the operation occurs, and there is a minimum of inertial force acting upon the parison at the time it is brought to upright position to be received by the blow mold.

Also, holding the parison by its bottom, and the transfer of a stiff parison, are obtained in this machine. When the transfer is in its upright position, the parison extends

vertically upwardly with its finish at the top of the blow molds. The blow molds engage at the neck of the finish, in the manner shown in Figs. 2 and 82, so that the blank projects from the top of the blow molds, and is supported at its top and at its bottom. True alignment of the parison in the blow molds is thus assured.

The parison remains in the blow mold, in the present illustration, for well over a quarter of a revolution and nearly five seconds, during which it can reheat to soften the skin formed in the long blank mold operation. It is not required to stretch down, so that substantially all of the formation of the parison for final blowdown is completed in the blank mold.

Following the extended reheat period, and at the twelve-o'clock position in Fig. 93, twelve and one-half seconds after the charging, the blow head starts down over the top of the blow mold. This is produced by the release of the roller 1178 of the blow head valve 1150 and the cam track 1181. As shown in Fig. 74, the valve cam roller 1178 is engaged by the track. As already described, this has meant that the piston 1124 was elevated. When the roller 1178 leaves the extension 1190 of the track, the air conditions are reversed, and compressed air, acting on the outer end of the valve plug 1156, forces it inwardly and introduces the radial port 1164 to the passage 1172 and the passage 1174 to valve compressed air to the upper line 1176 leading into the top of the cylinder 1110 above the piston 1124. At the same time, the other line 1175 from the lower part of the cylinder is ported through the peripheral groove 1165 with the exhaust 1167. The piston thereby is caused to descend to the dotted line position in Fig. 77, introducing the blow head 1130 over the top of the projecting finish of the ware. This blow head has a recess 1138 to receive the projecting finish, and the lower end of the head makes a tight fit with the top of the blow mold. It is self-sealing by the arrangement previously described.

With the blow head down, the port 1145, connecting with the axial passage 1144 of the piston rod 1125 (Fig. 77), is caused to register with the inlet port 1146 (Fig. 80) from the blowdown air line 1122, which receives air at reduced pressure. The blowdown for the finish of the ware then takes place. It produces the final ware out of the parison.

At approximately the two-o'clock position, fourteen and one-half seconds after the charging, the blow head valve control cam roller 1178 again engages the track 1028, as shown in Fig. 71, whereupon this valve is reversed to its position shown in Fig. 74, so that air is again introduced into the lower end of the piston 1124 and the upper end is connected to the exhaust. Thereupon this piston rises, removing the blow head from the blow mold. The blow mold then has its top open, and sufficient space is provided for the introduction of the take-out arm.

Shortly after the blow head is withdrawn, the blow mold begins to open. This operation is brought about by the engagement of the cam roller 1011 of the blow mold control valve 990 with its cam 1028. This shifts the valve plug 996 to the position of Fig. 47, whereupon air is introduced to the outer end of the piston 977, driving the piston inwardly as its other end is exhausted. This operation opens the blow mold, so that the same is open ahead of the three-o'clock position.

At the three-o'clock position, fifteen seconds after the charging, the take-out arm is introduced between the blow head and the ware, to engage the finish and withdraw the bottle.

At approximately the four-o'clock position, the transfer head is caused to return to the blank mold level. This operation has previously been described.

The complete cycle of any particular charge of glass in the illustration given is seen to take a total of one and one-half revolutions of the table. The take-out point is 180° away from the feeding point. The charge of

glass remains in the blank mold approximately 270°, and then is transferred to remain in the blow mold only slightly less than 270°, and in the neighborhood of 240°.

For illustration, by way of comparison of cycles between this machine and certain conventional machines, this machine, operating to produce sixty bottles per minute, will have a fifteen-second mold rate, which is to say that the time that any charge of glass remains in the molds from the charging point to the take-out point will be fifteen seconds. Assuming an angular distance that a charge is in the blank mold to be 210 degrees, it will be found that the total time for the foregoing operation will be about 5.8 seconds.

In the comparable machine now in the art, operating as nearly as comparably as it may, the mold rate will be ten seconds because such machine does not have an overlapping cycle that affords one and one-half full revolutions, but rather is compelled to accomplish the full cycle within the total space of one revolution usually made up of two one-half revolutions of two separate tables. Conventionally, one third of the angular travel in such conventional machine is devoted to parison formation, which applied to a ten-second mold rate means that the parison dwell is three and one-third seconds.

It may be seen from the foregoing that the parison dwell in the present machine is 5.84 seconds, as against 3.33 seconds. The present machine affords 175% of the parison dwell of conventional machines. Also, the mold rate of the present machine is half again as great. However, the present machine, operating under comparable conditions, will produce sixty bottles per minute as against thirty for the aforementioned conventional machine operated as stated. And any speeding up of the conventional machines, if possible, reduces both mold rate and parison dwell.

One of the limiting factors on conventional machines is the time required for the transfer operation. This results from a combination of conditions, one of which is that the conventional machine has a separate table for the blank molds from that employed with the blow molds. As a result, the two tables must stop and remain stopped long enough for the neck ring transfer to be made from the blank mold table over to the blow mold table. Any operation of such former machines requires this limiting factor to be included. In the present machine, the transfer time does not slow down the machine, because it takes place from between two sets of molds on the same table.

In the present machine, a change in speed of the machine, such as an increase in speed for lighter, smaller ware, will change the time of the transfer unless suitable adjustment is made. In other words, if the speed of rotation of the table is increased, the angular time represented on Fig. 93 for transfer will represent a smaller interval of time in seconds. If, with the lighter ware, such reduction in speed of the transfer does not adversely affect operation, no change in transfer time need be made. However, if the transfer time is inadequate under such speeded up conditions of the table, the transfer cams may be adjusted to stretch out the transfer interval by allotting them a greater angular space and consequently a greater time interval, possibly the same as an earlier setting with a slower table speed.

Such stretching out of the transfer interval normally may be made at the expense of the blow mold operation, or to the gain of the blow mold operation. This ordinarily affects only the length of the reheating period, which usually would be shorter anyway for the larger ware requiring longer transfer time. However, under certain extreme circumstances, it may be necessary to reduce the blank mold dwell somewhat in order to secure sufficient time for the transfer. In any case, it will be observed that it need not reduce the speed of

the machine or the total mold rate. This is an important advantage of the present machine and process.

In the foregoing example, it has been assumed that the total blank or parison dwell was 210° in angular distance. This 210° represents an approximate usual period of parison dwell for the machine. With it, the parison dwell is 175% of a comparable parison dwell on a conventional machine. As already noted, it is this long parison dwell that enables a stiff parison to be made.

The foregoing also illustrates the advantages of the overlapping cycle with a continuous machine. As already noted, the transfer operation does not limit the speed of the machine as a whole. Also, a protracted mold rate is obtained, and consequently better heat dissipation in the various stages of the cycle can be obtained, as well as greater over-all heat dissipation. The present machine accomplishes this despite the fact that it is producing many more bottles per minute than do conventional machines. The fact that the transfer time interval does not hold up the rotation of the machine thus makes it possible to speed up the machine or to slow it down, and thereby adjust its production to accommodate for different kinds of ware and to produce the maximum production for any particular kind of ware.

Another advantage of this process and machine is that square shouldered bottles may be made. With the machines heretofore known that transferred by neck rings, it is necessary to have a sufficiently extending neck to accommodate the rings. Hence it is the conventional practice on square shouldered bottles to form a somewhat elongated neck, which gives depressions in the shoulders adjacent the neck, which depressions must be removed in the blow molds. This is an obvious disadvantage and results frequently in production of shoulders that are rounded rather than square. It also results in weak spots or heavy spots at these points.

In the present machine, the absence of neck rings for the transfer makes it possible to produce finishes with very short necks that merge almost directly into the shoulders of the bottles. The shoulders may be as square as desired. The transfer is made by holding the bottom of the bottle so that it puts no limitations upon the styling of the finish.

Installation adjustments

It is necessary to have certain parts of the machine capable of change. For example, molds must be changeable to make ware of different shapes and sizes.

The mold sets, both blank and blow molds, may be withdrawn as units. The screws 240 that hold the blocks 236 to the table 190 are removed, and the air connections released, whereupon any blank mold may be withdrawn as a unit including its power cylinder and valve. Any blow mold unit may likewise be withdrawn. As the blocks 236 are all identical, this makes possible the quick removal of any mold and the substitution of another one. The several blank mold units are all interchangeable, as are the blow mold units. In replacing one unit with another, complete and accurate alignment is obtained by the engagement of the mold pin in a hole 209 or 963, and the saddling of a block in a yoke 252 or a notch 960. Thereafter, the screws are tightened merely as holding means. No drive pins or the like are required. These positioning elements are sufficiently removed from the highly heated parts to be unaffected by expansion.

A blank mold may be removed from its pin 245 by disconnection of the links 259, and the lifting of the mold sections from the pin 245. Thereafter, a different mold may be installed over the pin 245 and properly connected to the yoke. Conventionally, all molds have hinge ears of the same size and shape. The changing of a blow mold follows a like procedure.

If the mold newly installed is substantially different in length, it may be necessary to withdraw the spacer 383 (Fig. 33), and, if a spacer is required on the new mold, to insert a spacer of different length. If the shape of the finish part of the ware is substantially different, different neck rings will be used and possibly a different plug assembly 395 may be required. Where the spacer 383 is changed, the extension 381 of the plunger will be replaced by one of a size corresponding to the new spacer ring 383. This latter change is easily accomplished when the head 395 is withdrawn from the top of the spacer, and the spacer itself is removed.

In the installation of molds into this machine, one of the controlling factors is the proper seating of the transfer head into the blank and the blow molds. A transfer head 775 will be installed, which head most nearly approximates the spacing requirements between the member 742 and the blank and blow molds. Thereupon, the machine will be operated until the transfer head is down to the position shown in Fig. 49 and is seated in the top of the blank molds. Thereupon, the ring 248 surrounding the collar 247 is loosened. The collar 247 is then turned to raise or lower the mold to secure precise seating of the transfer head in the top of the blank mold, after which the ring 248 is again tightened. This adjustment is accommodated for by lost motion vertically in the hinges of the mold to the yoke 258.

When the foregoing adjustment is complete, the head for the blank mold is properly adjusted. As previously noted, the spacer sleeve 383 and the extension 381 on the plunger are chosen so as most nearly to approximate the proper spacing of these parts to give proper engagement of the head with the blank mold. It is required for most advantageous operation of this machine that the cap 395 on the head be raised slightly as the mold halves close over it. Such raising permits the mold sections to be properly aligned one with the other, and also secures the best fit of the parts for sealing purposes. Likewise, the dropping away of the cap 395 when the mold sections open relieves the mold sections of any frictional engagement with the head almost as soon as the mold sections begin to crank open, with the result that smoother opening operation results and less likelihood of sticking of the parison to one or the other of the mold halves is present.

In order to secure this adjustment for the proper amount of lifting, the latching dog 387 is rocked against its spring 389 to free it from the peripheral teeth on the collar 385. Thereupon, the collar is turned until the spacer 383 and the cap 395 are at the proper elevation to achieve the foregoing desired results. As already described, the seating of the plunger itself is under the influence of air below the piston 343. Hence, this piston is adequately self-adjusting for the foregoing purpose.

The baffle head likewise must be suitably adjusted to seat firmly on the top of the mold. This may be accomplished by the loosening of the screws 526 and 527 (Fig. 42) and the sliding of the entire arm 523 on the column 521, followed by the re-tightening of the screws when the head is in its proper position. A fine adjustment of this may be made by loosening the nut 531 and turning the shaft 530. This latter adjustment is also convenient for proper positioning of the head 540 relative to the mold, in respect to its proper angular position about its axis of rotation. In fact, this is the prime purpose for this fine adjustment, because the baffle head is lowered by air pressure and will therefore seat with some tolerance in the adjustment of the arm 523. In order, for example, to get the proper angular disposition of the head 540 for oval bottles, the nut 531 is loosened and a tool is inserted in the kerf in the shaft 530 and the same is turned until the head is properly aligned. In this operation, the screws 535 are always turned down so that there is a frictional

holding of the shaft 530 against rotation except when force is applied thereto. By this means, the shaft will retain its position to which it is adjusted, and thereafter the nut 531 may be turned down to lock it in that position.

The baffle may be adjusted in a horizontal plane by loosening the screws 516, and then adjusting the screws 517 until the baffle seats accurately in the recess in the mold. Then the screws 516 are re-tightened.

If the shape of the baffle plate requires change, it is only necessary to remove the spring 541 from the necks on the pins 539. Whereupon, the head 540 and the attached pins 539 may be withdrawn from the plate 537. A new head may then be inserted and the spring returned to its place. It has already been described how the clearances in the head provide for its self-centering into the mold when it is closed.

The transfer head is likewise provided for quick change to accommodate alteration in mold size. A transfer unit may be replaced easily by removing the screws 691 that attach the unit between adjacent columns 490. Then the unit is lifted to clear the ridge 690 on the columns, whereupon it may be withdrawn radially outwardly from the machine. A new unit may be installed by reversing the process. The engagement of the arcuate edges of the arms 686 and 687 with the ridges on the columns is one that automatically aligns the parts.

A substitute vacuum head 775 may easily be made, as shown in Figs. 78 and 79, by twisting the head off of the two spring retained pins 765, as permitted by the presence of the notches 770. Thereupon, a different head of proper length or shape or size may be installed.

Other preliminary adjustments will include, with respect to each transfer mechanism, the adjustment of the turnbuckle 727 to regulate the maximum outward position of the piston and maximum downward swinging of the vacuum head. The maximum inward position of the piston and maximum upward position of the head may be adjusted by the abutment screw 763 acting on the piston. Likewise, the screws 758 (Fig. 50) may be adjusted to regulate the angular position of the vacuum head about the shaft 747, to give proper seating on the molds. The sleeves 711 may be adjusted to determine the point at which the deceleration of the transfer begins, and the amount of resistance of the springs 719, and hence the degree of retardation of the transfer operation.

The blow molds may be adjusted vertically by the collars 970 to fit properly with the transfer heads. The blow heads are adjusted by the knobs 1104 acting upon the screws 1103.

If the changes in the mold are great, it may be necessary to substitute new cooling air nozzles on the column 499. If the blank mold is very much longer or shorter than one previously used, the spacer 497 (Fig. 83) may be changed for one of proper size. The nozzle elements 496 and 498 may easily be changed, as they are held by screws into place. The nozzles 1067 and 1068 may easily be replaced, because they are merely fitted over the pins 1066. Similarly, the nozzles 1078 and 1079 may easily be replaced, because they are merely engaged over the pins 1075. Such changes will provide nozzles that properly accommodate the size and shape of molds employed.

Timing adjustments

All adjustments of the timing of the various elements of the mechanism, that may be required during the operation of the machine, may be made during the operation. Certain adjustments, however, are not normally required during the operation, and therefore are made only when the machine is initially set up for operation. For example, the operation of the blank mold baffle head does not normally require adjustment during the cycle, and may be taken as a datum upon which the other parts of the cycle may be based.

The operation of the baffle head is controlled by the composite cam track 615 (Fig. 6). The baffle is caused to

come off when the baffle cam roller 566 (Fig. 29) rides up onto the first element of the cam track 615. This consists of the strip 623 (Fig. 8), which may be adjusted along the fixed track 615 by loosening the screws 624, shifting the track 623, and then re-tightening the screws. Sufficient time is provided between the completion of the counterblow in the blank mold and the introduction of the transfer head to the top of the mold to provide ample time for the removal of the baffle head for the introduction of the transfer head. Hence the track element 623 may be adjusted at the beginning of a set-up of the machine, and this normally will be adequate for any operation of the machine. The track 623 must lead the advance section 821 of the vacuum track, and must lead the starting edge 918 of the transfer cam element 916 sufficiently that the baffle head will be out of the way of the transfer head.

The other end of the baffle cam track is likewise adjustable, it consisting of a strip 626 that is secured to the strip 618 by screws that engage in slots, as aforesaid. The point at which the baffle track ends is the point at which the baffle comes onto the blank mold. This must necessarily come between the end of the vacuum pull-down on the blank and the start of the counterblow. However, it may constitute the datum point for the adjustment of the plunger and vacuum operations, and the counterblow for practically all molds that will be used on the machine will find sufficient time on the length of the cam 635. In other words, it is sufficient to have a preliminary positioning of the final end 626 of the baffle cam track and not to provide for adjustment thereof during operation.

Prior to the charging of the blank mold, it must be closed. This is accomplished by the cam structure shown in Fig. 46. For the present, it will be assumed that the blank mold is properly closed, prior to the introduction of a charge.

It will be noticed from Figs. 6 and 11 that at the time the charge is introduced into the blank mold the vacuum valve 478 will be open, and vacuum will be drawn onto the mold. This will assist in drawing the charge of glass into the bottom of the blank mold, as already described, and will be available at the instant the charge is delivered to the mold, regardless of possible variations in the coordination of the feeder. This vacuum must continue for a sufficient length of time to insure the formation of the finish of the blank. It may be necessary, owing to variations in the consistency of the glass, or for other reasons, to alter the duration of this vacuum flow. Furthermore, it must be coordinated with the upward operation of the plunger, so that it will be available when the plunger opens its port 460 to the vacuum supply, and will be off when the plunger is withdrawn so as not to injure the skin of the finish.

For these purposes, the vacuum track has two adjustments. The first involves the rotation of the hand wheel 598 (Fig. 11) to move the advance strip 579 of the vacuum track to change the starting point of the vacuum stroke, and to insure that vacuum is properly available as soon as the charge is introduced into the closed blank mold. This adjustment assures proper vacuum when the charge is received, regardless of variations in the speed of the machine, or the length of the path that must be evacuated. The other adjustment of the vacuum track is obtained by rotation of the thumb nut 592 (Fig. 11), and the consequent displacement of the final cam track strip 580 to vary the end point of the vacuum stroke. It may be considered that these two variations or adjustments are made relative to the operation of the baffle, because, for purposes of description, it has been assumed that the baffle constituted the datum point for the adjustments. The vacuum must be off when the plunger is withdrawn, lest damage to the finish occur. Hence, it is coordinated with the adjustment of the plunger cam track.

The operation of the plunger for the blank mold is subject to three regulations. This plunger must be moving up at the time the charge is introduced into the mold, so that the glass will not descend through the mold. On the other hand, it is necessary to have the charge of glass descend to the bottom of the neck rings completely, in order to form the finish without overpress or underpress.

To start the plunger and have it in the proper position at the time the charge of glass is introduced into the mold, the leading track element 605 of the plunger track (Fig. 11) is adjustable by means of the hand nut 610. The hand nut 592 determines the point at which the plunger shall start down.

However, the track element 605 merely determines the point at which the valve 354 shall shift. When this valve is up (Fig. 26), the air is introduced (through the needle valve 368) to the lower end of the cylinder below the piston 343. The start of the upstroke of the plunger and the speed with which it travels, being functions of the aforementioned track adjustment and the adjustment of the valve 368, should be regulated so that the plunger is not quite seated at the time the charge is brought into the mold. This will permit the glass to fit well into the neck rings, and will avoid underpress. The plunger must be far enough up to prevent overpress. The speed of the plunger must be regulated by the valve 368 to prevent bouncing of the glass off the plunger, and updriving of the glass out of the finish. Thus the cam track element 605 (Fig. 11) is preset to insure that the plunger can be up at the proper time, and the valve 368 is adjusted during operation to obtain proper speed and position of the plunger at the point of introduction of the glass charge.

As already noted, the plunger descends at a time co-ordinated with the withdrawal of the vacuum and the return of the baffle by the adjustment of the end of the track element 606 through the hand nut 613. When the plunger valve cam roller leaves this final track element, the plunger will descend rapidly under the influence of the coil spring 344.

When the plunger is withdrawn, the shell of cooled glass that was formed about its plug is immediately re-heated by the remainder of the hot glass in the charge. The baffle comes on an instant later under the control of the baffle valve cam roller 566, which leaves the end of the baffle track, which latter is initially adjusted as already described.

Adequate time is provided in these operations to permit the shell or skin, formed around the plunger plug, to reheat by the time the counterblow begins. The beginning of the counterblow is determined by the setting of the end 640 of the blowback track 635, which is initially adjusted as already described. When the cam roller 452 of the counterblow valve engages the track element 640, the counterblow will begin. It continues for approximately 100°, this being in point of time a much greater period than is given to producing parison in former machines. After the counterblow air has been cut off, at a time fixed by the adjustment of the end track element 642, the blank mold continues its travel for some 28°, more or less, when the baffle is removed. This time of parison dwell is ample to compress the glass firmly in the blank mold and retain it there to provide a thick skin that is relatively even over the parison, with less difference between the finish and the remainder of the parison. It makes a parison having rigidity permitting its transfer to the blow mold without substantial deformation.

The baffle arm is caused to withdraw the baffle plate by the engagement of the baffle valve cam roller 566 with the initial end of the baffle cam track 615. This end is adjustable, as are the ends of the counterblow cam track 635.

Thereafter, the transfer head starts down. The point at which it starts down is adjustable by adjusting the

position of the cam track element 916 (Figs. 57-62). This adjustment is accomplished by the thumb screw 934 (Fig. 1) acting through the worm 931 of the gear 930, which rocks the crank arm 925.

During the operation of the transfer head from its upper to its lower position, the vacuum is introduced thereto by the engagement of the valve 813 with the cam track 818, and more particularly with the end strip 821 of this cam track. This point is adjustable by the thumb nut 825 (Figs. 6 and 8), which shift this initial vacuum cam track rail 821 relative to the fixed rail 819. This vacuum should be on at the time the transfer head is introduced to the blank mold.

The speed of downswing of the transfer head is controlled by the shape of the cam element 916 (Figs. 57, 62, Sheet 13). This element is individually replaceable. If the machine is speeded up, it may be necessary to advance the cam 916 by the thumb screw 934, as some time is inevitably required to build up the air pressure in all cylinders. It is for this reason, among others, that the various air operated devices are provided with adjustable cams; and those requiring close synchronization are adjustable during operation. The transfer head must be down in time to hold the parison when the blank mold opens.

Likewise, the opening of the transfer vacuum is controlled during operation by the hand screw 825. This makes it possible to assure operating vacuum on the transfer head when it should engage the parison, regardless of such changes as variations in speed of the machine.

The transfer operation consists in a return of the transfer head to its upper position, with the parison held thereto, by vacuum on the vacuum head while the latter is interfitted with the completed bottom of the parison accurately shaped by the baffle head. As will appear, this start of the transfer operation is adjusted to occur after the blank mold begins to open, and after sufficient time has elapsed for the vacuum head of the transfer mechanism to seize hold of the bottom of the parison. The other transfer cam track element 886 is likewise adjustable, this adjustment being made by the thumb nut 905 that rocks the shaft 900 to determine the point at which the transfer operating cam is released. The speed of this release is a function of the slope of the edge 888 of this cam element 886, which is a separate and replaceable part. The speed of the final part of the transfer operation is also regulated by the adjustment of the sleeves 711 to vary the resistance afforded by the spring 719 on the transfer mechanism itself.

The blank mold must begin to open prior to the shift of the transfer mechanism. This requires a shift of the blank mold valve 270, which is produced by engagement of its roller 291 with the initial part 307 of the cam structure shown in Fig. 46. The point at which this operation begins is initially set by the arcuate displacement of the cam track element 307 on the screws 310. This cam track element 307 has slots 309 engaging over the screws 310. It may be adjusted by turning the thumb nut 323, which rotates the shaft 316, and, through the connecting arms, shifts the track element. This coordination may be made during operation. The blank mold will begin to close when the valve cam roller leaves the end element 305 of this track. This will take place at a time sufficiently ahead of the charging point to have the blank mold completely closed when the charge is introduced into the mold.

The blow mold must be open at the time the take-out takes place. This is timed by the cam mechanism shown in Figs. 71 and 72. The blow mold is opened by the engagement of its valve cam roller 1011 with the cam mechanism in Fig. 71. The opening point is determined by the preliminary setting of the cam track element 1028, which, as will appear, may be made when the machine is initially set up through the adjustment of this element provided by the slots 1025. The end of this opening of the blow mold is determined by the adjustment of the cam track element 1032. This is regulated by the shaft

1043 under control of the thumb nut 1048, this shaft being connected through the crank 1041 in the link 1040 with the rockable upper member 1030 supported in the groove 1022 of the member 1018. By this arrangement, the point at which the blow mold closes may be adjusted to take place only after the transfer is completed.

After the blow mold is closed, the vacuum must go off the transfer head. This occurs when the transfer vacuum valve 809 is closed by the release of its cam roller 813 from the track 818. The point may be initially adjusted by the adjustment of the end cam track element 830. This is normally an initial adjustment made when the machine is set up for operation, and is designed to occur substantially simultaneously with or slightly before the complete closure of the blow mold.

The parison is usually permitted to rest in the blow mold for a substantial period of time prior to the blow-down. This is to permit the skin on the parison to reheat from the hot glass it contains. The point at which the blow head starts down is determined by the cam structure shown in Fig. 73 which releases the cam roller 1178 of the control valve plug 1156, so that the blow head will descend. More particularly, this point is determined by the adjustment of the cam element 1190 (Fig. 73) which may be regulated by the shaft 1194. A shorter cam element 1190 may be applied for much longer blowdown period and shorter reheat period, such as may be desirable with large ware. The cam 1190 may be adjusted by the thumb nut 1200 at the top of the machine. The blow head descends promptly, and when it reaches its lower position automatically valves the blowdown air into the blow head. The final blow takes place as long as the blow head is down, and, therefore, is controlled by the cam of Fig. 73. The cam roller 1178 remains released until it reaches the starting cam track 1186. This starting cam track is adjustable by the engagement of the slots 1187 about the screws 1188. This adjustment is normally made when the machine is set up, so that the conventional adjustment of both the reheating period and the final blow period is made by the previously mentioned adjustment of the thumb nut 1200, which provides a division of the total reheating and final blow periods. From the nature of the construction of the blow head, the blowdown air is cut off at the start of the withdrawal of the blow head. Almost immediately thereafter, the blow mold begins to open by the engagement of its control valve cam roller 1011 with the track element 1028, as aforesaid. The blow mold then completes its opening for the ware take-out.

The foregoing completes a cycle of one bottle, it being understood that the identical cycle is provided for each of the successive molds.

It will also be understood that the conventional pressure reducing valves 1235 and 1236 may be adjusted to provide the proper air pressure to control the speed of the counterblow and the blank mold and the blowdown in the finish mold.

From the foregoing it may be seen that this invention provides for faster production of better ware, with less complication than heretofore. It enables the manufacture of ware to be supervised by one man. It accomplishes its objectives previously set forth.

What is claimed is:

1. In a machine for making hollow containers, or the like, of glass, said machine having a plurality of blank molds, a plurality of finish molds, there being a blank mold for each finish mold, means for coordinately moving said molds, each blank mold having means to form a finish at one end of the parison into at least substantially final shape, and having means to form a finished portion at the opposite end of the parison, the parison being substantially, between the finish at the one end and the finished portion at the other end, of the length of the final ware, transfer means for each pair of blank and finish molds to transfer the parison from the blank mold to the finish mold, the finish mold being adapted to en-

gage the parison adjacent the finish at the one end thereof and to support the same at the finished portion adjacent the other end thereof, and blow head means for each pair of blank and finish molds engageable over the finish

5 at the one end of the finish mold to blow the parison out to fill the said mold: a separate power unit for operating each blank mold, each finish mold, each transfer means, and each blowhead means, a separate controlling device for each of said power units, and timing means for actuating said controlling devices, said timing means comprising separate composite cam means for each group of controls associated with the blank molds, the finish molds, the transfer means, and the blowhead means, respectively, and individual manually operable means connected to 10 each of said composite cam means for adjusting the latter at will during the operation of the machine.

2. In a glass machine, a rotatable support, a blank mold on said support, the support being adapted to move the blank mold in a circular path and across a charging point 20 at a fixed location in the travel thereof, means cooperable with the blank mold to form a parison therein, a transfer mechanism on the support, a second mold on the support, the blank mold and second mold being superposed one above the other, the transfer means being adapted to engage the parison after it has been fully formed in the blank mold and to move it to the second mold, composite cam means for timing the transfer to occur after the blank mold has traveled at least 180° from the charging point and before its return thereto, means to complete 25 the glassware in the second mold, the second mold being conveyed to a takeout point at least substantially 180° from the charging point, the support being rotatable at a constant rate of speed providing for appropriate forming and subsequent cooling of the parison in the blank mold 30 and for appropriate reheating of the parison and for subsequent completion of the ware in the second mold, and means for coordinately varying the relationship between the period of time available for cooling the parison in the blank mold and the period of time available for reheating 35 the parison in the second mold, said latter means including means manually operable during rotation of the support for adjusting the composite cam means and thereby varying the time of transfer within the aforesaid limits, transferring, and taking out within the visibility 40 range of a person on one side of the machine.

3. A machine for making glassware, including a base, a table rotatably mounted on the base, a plurality of columns rising from the table outwardly from the center thereof, said columns being supported upon said rotatable 50 table, a supporting member attached to and joining the several columns above the rotatable table, a member joining the tops of the several columns, a center column rising from the base, said top member having a bearing on said center column, said rotatable table, columns, supporting member and top member constituting a movable framework for glass forming apparatus.

4. A machine for making glassware, including a base, a table rotatably mounted on the base, a plurality of columns in circular array mounted on and rising from the 55 table, means connecting the columns above the table, interfitting locating means between each of the columns and the table to accurately position the individual columns relative to the table, securing means to hold the columns and connecting means accurately together, fixed locating 60 means on each of the columns intermediate the ends thereof, a transfer mechanism disposed between each pair of adjacent columns and supported thereon, and fixed locating means on each of the transfer mechanisms interfitting with said fixed locating means on the adjacent supporting 65 columns for properly positioning the transfer mechanisms with respect to the table.

5. A machine for making glassware, including a base, a table rotatably mounted on the base, a plurality of columns in circular array mounted on and rising from the 70 table, means connecting the columns above the table, in-

terfitted locating means between each of the columns and the table to accurately position the individual columns relative to the table, securing means to hold the columns and connecting means accurately together, fixed locating means on each of the columns intermediate the ends thereof, a transfer mechanism disposed between each pair of adjacent columns and supported thereon, fixed locating means on each of the transfer mechanisms interfitted with said fixed locating means on the adjacent supporting columns for properly positioning the transfer mechanisms with respect to the table, a mold disposed below each transfer mechanism, means supporting the molds on the table, and interfitted means between each mold and the table to position the molds accurately on the table for periodic interfitted engagement with their respectively associated transfer mechanisms.

6. In a glass machine, a base, a support mounted for rotation on the base, a mold head mechanism mounted on the support for rotation therewith, said mold head mechanism comprising a mold head reciprocable plunger in the mold head, and a piston for moving the plunger, vacuum passage means in the mold head for extending a vacuum to an associated mold, blow air passage means in the mold head for conducting blow air to the associated mold, compressed air passage means for energizing said piston and plunger, said latter means including adjustable passage restricting means for regulating the speed of movement of the piston and plunger, a valve group connected with said head, said valve group including a valve for controlling the flow of compressed air for operating the piston and the plunger, a valve for controlling the flow of blow air to the blow air passage means, and a valve for controlling the vacuum for the vacuum passage means, each of said valves having a depending stem projecting downwardly toward the base of the machine, and cam means interengagable between said stems and said base for causing said valve means to operate in timed relation as the mold head means moves over the base.

7. In a glass machine, a base, a table rotatably mounted on the base, said table having a vacuum chamber therein, a transfer mechanism supported on the table, said transfer mechanism having a vacuum passage therein, a mold head mechanism supported on the table, said mold head mechanism having a vacuum passage therein, individual vacuum passage means connecting said vacuum passages, respectively, with said vacuum chamber, a valve in each of said vacuum passage means for selectively extending vacuum from the vacuum chamber to the respective vacuum passages, and cam tracks on the base below the table, said valves having cam actuating members depending below the table for engagement with said tracks during rotation of the table.

8. In a glass machine, transfer mechanism for moving a glass article from a blank mold to a finish mold, said transfer mechanism including a driving member, a base upon which the driving member is supported, a rocking lever, a glass holding head pivotally supported on the rocking lever, means connecting the rocking lever to the driving member for rocking the rocking lever a predetermined distance upon movement of the driving member, and linkage means connecting the transfer head to the base for causing additional pivoting of the transfer head during the rocking of the rocking lever.

9. In a glass machine, a transfer mechanism comprising a base, a driving member, a rocking lever pivoted to the base, means connecting the driving member to the rocking lever to rock the same, a transfer holding means pivotally mounted on the rocking lever, said driving member being adapted to rock the rocking lever approximately 90° on the base, and a linkage connection between the base and the transfer holding means for causing the transfer holding means to rock 180° when the rocking lever is being rocked 90°.

10. In a glass machine, a transfer mechanism comprising a base, a driving member, a rocking lever pivoted to

the base, means connecting the driving member to the rocking lever to rock the same, a transfer holding means pivotally mounted on the rocking lever, said driving member being adapted to rock the rocking lever approximately 90° on the base, and a linkage connection between the base and the transfer holding means for causing the transfer holding means to rock 180° when the rocking lever is being rocked 90°, said linkage connection including a pivotal support on the base, a link fixed to the head and 10 having a slot engaging said pivotal connection.

11. In a transfer mechanism for glassware, a base, a reciprocating driving member mounted on said base, a crosshead connected to said driving member for movement therewith, said crosshead being slidably supported on 15 the base, spring cushioning means engageable by said crosshead at one end of the movement thereof, a rocking lever pivotally mounted on the base, a glass holding transfer head pivotally mounted on the rocking lever, and means connecting the rocking lever and the crosshead for 20 rocking of the lever upon movement of the driving member.

12. In a transfer mechanism for glassware, a base, a reciprocating driving member mounted on said base, a crosshead connected to said driving member for movement therewith, said crosshead being slidably supported on 25 the base, spring cushioning means engageable by said crosshead at one end of the movement thereof, a rocking lever pivotally mounted on the base, a glass holding transfer head pivotally mounted on the rocking lever, means connecting the rocking lever and the crosshead for rocking of the lever upon movement of the driving member, and means for adjusting the force of said cushioning means.

13. In a glassware forming machine, a transfer mechanism comprising a base, a driving member, a rocking lever pivotally mounted on the base, a pivotal support on the base for the rocking lever, means connecting the rocking lever and the driving member for rocking of the lever upon movement of the driving member, a transfer head pivotally mounted on the rocking lever, air flow means in 35 the pivot for the rocking lever, an air passage connecting with said air flow means in said pivot, said air passage extending through the lever to the transfer head, and air flow means in the transfer head connected with said air 40 flow means.

14. In a transfer mechanism, a base, a driving member, a rocking lever pivotally mounted on the base, a pivotal support on the base for the rocking lever, means connecting the rocking lever and the driving member for 50 rocking of the lever upon movement of the driving member, a transfer head pivotally mounted on the rocking lever, air flow means in the pivot for the rocking lever, an air passage connecting with said air flow means in said pivot, said air passage extending through the lever to the transfer head, and air flow means in the transfer head connecting with said air passage, said air flow means in the transfer head including a movable connection for 55 the provision of air flow from the head to said air passage.

15. In a glass machine, a transfer device including a transfer head adapted to fit into a complementarily shaped space in a mold, a rockable member upon which the transfer head is mounted, means for rocking said member to move the transfer head, and a lost-motion connection between the transfer head and the rockable member to permit the transfer head to move with limited movement with respect to the member, whereby it may fit itself into the space in the mold, said lost-motion connection including resiliently mounted conical means biasing the head toward 60 centered engagement with the member.

16. In a glass machine, a transfer device including a transfer head adapted to fit into a complementarily shaped space in a mold, a rockable member upon which the transfer head is mounted, means for rocking said member to move the transfer head, and a lost-motion connection between the transfer head and the rockable member to 70

permit the transfer head to move with limited movement with respect to the member, whereby it may fit itself into the space in the mold, the transfer head having an air passage therethrough, an air passage in the rockable member connected with the air passage in the head, the head and the rockable member having sealing surfaces engageable with each other, and the lost-motion connection comprising means holding the transfer head to the member to cause tight fitting together of said sealing surfaces, said means permitting the movement of the head with respect to the member without breaking the sealing surfaces apart and biasing the head toward centered engagement with the member.

17. In a glass machine, a mold having sections that open and close, the mold sections having recesses to receive an end closure, a transfer mechanism including a vertically rockable member and a transfer head attached thereto, the transfer head having a shape to engage in the recesses within the mold to form the end closure, and means for snap-on attachment of the transfer head to the rockable member.

18. In a glass machine, a mold having sections that open and close, the mold sections having recesses to receive an end closure, a transfer mechanism including a vertically rockable member and a transfer head attached thereto, the transfer head having a shape to engage in the recesses within the mold to form the end closure, and means for snap-on attachment of the transfer head to the rockable member, said last named means including spring pressed pin members on one of said members and slots on the other engageable over the spring pressed pin members, said pin members being adapted to urge the transfer head in centered relation against the rockable member.

19. In a glass machine: a transfer device for reverting glassware parisons and moving them from a blank mold to a finish mold; the transfer device including a transfer swinging head, a bellcrank lever supporting the head, a wrist pin on which the bellcrank lever is mounted, a vacuum passage axially extending in the wrist pin and connecting through the wall thereof into the bellcrank lever and extending through the latter for connection into the head.

20. In a glass machine: a transfer device for reverting glassware parisons and moving them from a blank mold to a finish mold; the transfer device including a transfer swinging head, a bellcrank lever supporting the head, a wrist pin on which the bellcrank lever is mounted, a vacuum passage axially extending in the wrist pin and connecting through the wall thereof into the bellcrank lever and extending through the latter for connection into the head, the head being swiveled onto the bellcrank lever, and means to maintain vacuum communication between the head and bellcrank lever during the swiveling of the head.

21. In a glass machine: a base, a rotating table mounted on the base, a transfer device mounted on the table for reverting glassware parisons and moving them from a blank mold to a finish mold; the transfer device including a transfer swinging head, a bellcrank lever supporting the head, a wrist pin on which the bellcrank lever is mounted, a vacuum chamber, a vacuum passage communicable therewith axially extending in the wrist pin and connecting through the wall thereof into the bellcrank lever and extending through the latter for connection into the head, the vacuum chamber being contained within the table, and extending around the outer edge of the same.

22. In a glass machine: a base, a rotating table mounted on the base, a blank mold mounted on the table, a finish mold mounted on the table, a transfer device mounted on the table for reverting glassware parisons and moving them from the blank mold to the finish mold; the transfer device including a transfer swinging head, a bellcrank lever supporting the head, a wrist pin on which the bellcrank lever is mounted, a vacuum chamber, a vacuum passage communicable therewith axially extending in the wrist pin

and connecting through the wall thereof into the bellcrank lever and extending through the latter for connection into the head, the vacuum chamber being contained within the table, and extending around the outer edge of the same, and a cooling air chamber within the table, there being hollow columns extending upwardly from the table for conducting cooling air to the molds, and the transfer devices being mounted on the columns for support.

23. In a hollow container ware forming machine: a table, a blank mold on the table adapted to form an inverted parison with a finished upwardly disposed end surface; a transfer device having a swingable member on the table, and a vacuum head on the member, the vacuum head having a surface complementary to the end surface of the parison, means to provide a vacuum drawn through the head surface so it may engage the end of the parison and hold the parison while the transfer member swings to revert the parison, the vacuum head having a resilient yieldable connection with the swingable member; finish mold sections adapted to close onto the parison and transfer head; and interfitting self-positioning elements on the finish mold sections and transfer head whereby when the finish mold sections close on the head they will automatically position it so that it constitutes a properly located bottom plate for the finish mold.

24. The combination of claim 23 wherein the self-positioning elements comprise a tapered and shaped outer end on the head and complementary grooves in the mold sections.

25. In a glass machine: a base, a table rotatably mounted on the base; a transfer device on the table, the transfer device including a support and a rocking lever, a pivot mounting for rockably supporting the rocking lever on the support; a glassware transfer head, a rocker mounting for rockably supporting the head on the rocking lever; a slotted link fixedly attached at one end to the transfer head, and a bracket fixed to the support and having a portion fitting through the slot of the link; a motor for rocking the rocking lever; and means operated by movement of the table for governing operation of the motor, the rocking lever being moved through an angle of 90°, and the engagement of the bracket and slotted lever being at a point that is on a chord of the arcuate movement of the rocker mounting of the transfer head.

26. In a transfer mechanism for glassware, a base, a reciprocating driving member mounted on said base, a crosshead connected to said driving member for movement therewith, said crosshead being slidably supported on the base, spring cushioning means engageable by said crosshead at one end of the movement thereof, a rocking lever pivotally mounted on the base, a glass holding transfer head pivotally mounted on the rocking lever, means connecting the rocking lever and the crosshead for rocking of the lever upon movement of the driving member, and means interconnecting the base and the transfer head to cause the head to pivot on the rocking lever during the pivoting of the rocking lever on the base.

27. The combination of claim 26 with means for adjusting the force of the cushioning means.

28. In a glassware forming machine, a transfer mechanism comprising a base, a driving member, a rocking lever pivotally mounted on the base, a pivotal support on the base for the rocking lever, means connecting the rocking lever and the driving member for rocking of the lever upon movement of the driving member, a transfer head pivotally mounted on the rocking lever, a link interconnecting the transfer head and the base, air flow means in the pivot for the rocking lever, an air passage connecting with said air flow means in said pivot, said air passage extending through the lever to the transfer head, and air flow means in the transfer head connected with said air passage.

29. The combination of claim 28 wherein the air flow

means in the transfer head includes a movable connection for the provision of air flow from the head to the air passage in the rocking lever.

30. In a method of making glassware upon a rotating glass machine having a set of blank molds around it at one level and a set of finish molds around it at another level thereby providing a plurality of mold steps each having a blank mold and a finish mold: the steps of charging a blank mold at a charging point in the rotation of the machine, with a charge of glass; forming an inverted parison in the blank mold with a portion of its top surface shaped like the final ware, and with its lower parts finished; holding said parison in the mold until it becomes relatively stiff to withstand subsequent transfer to the finish mold; engaging the finished top surface of the stiff parison by interfitting a transfer head therewith and drawing a suction thereon; opening the blank mold; swinging the parison to reverted position while holding the suction thereon, and enclosing the same with the suction head in the finish mold; reclosing the blank mold and recharging it while the parison is thus within the finish mold, so as to prepare a new parison; forming the parison into finished ware in the finish mold while formation of the subsequent parison is occurring in the blank mold; opening the finish mold and withdrawing the completed ware in time to make the transfer head available to engage the subsequent parison by the time of the completion thereof; and thereafter repeating the cycle.

31. In a glass machine: a rotatable base having upper and lower mold sets each comprising a plurality of molds disposed around the base so that each upper mold may be interoperated with a lower mold; one set of molds being parison molds and the other being finish molds; the base being rotatable so as to bring each parison mold past a charging point, and each finish mold past a withdrawal point; a baffle for each parison mold; a transfer mechanism for each pair of interoperable molds, each transfer mechanism having a head engageable with a parison in the parison mold, and means to swing the head from the parison mold to the finish mold and back, the head being adapted to comprise a portion of the finish mold; means to bring the baffle onto its blank mold at a selected point in the rotation of the base and to hold it there for a portion of said rotation, means to withdraw the baffle, means to operate the transfer head swinging means to introduce the transfer head onto the parison in the parison mold after the baffle is withdrawn, means to open the parison mold, means to operate the transfer head swinging means to swing the head and parison to revert the latter after the parison mold is opened, means to close the finish mold onto the parison and the transfer head and to maintain them thus until the base has made more than one revolution from the

charging point; means to reclose the blank mold after the transfer and means including the rotatable base to bring it again to the charging point to repeat its cycle; and means to open the finish mold, so that the ware may be withdrawn, and means to operate the transfer head swinging means to return the transfer head to the blank mold after the baffle has been withdrawn from the same in the next subsequent cycle of the blank mold.
